CHARLES W. BREWSTER, OF NEW YORK, N. Y., ASSIGNOR, BY MESNE ASSIGNMENTS,
TO SPRAGUE SAFETY CONTROL AND SIGNAL CORPORATION, OF NEW YORK, N. Y.,
A CORPORATION OF VIRGINIA

AUTOMATIC TRAIN CONTROL AND SIGNAL

Application filed January 6, 1916. Serial No. 70,579.

This invention is a system of train control wherein provision is made for meeting the various conditions of service calling for freedom in the movement of the vehicle under normal or full speed while advising the driver or motorman of the condition of the track ahead; further, should the vehicle attempt to approach an occupied block ahead at too great a speed, the progress of the vehicle towards said occupied block is automatically reduced to a lower speed, means being provided so that the distance intervening between the vehicle and the occupied block will determine the speed at which the vehicle may travel, or in other words, the speed of a following vehicle while approaching a preceding vehicle is reduced proportionately to the distance separating the two said vehicles, and thereafter the driver or motorman is permitted to proceed up to the entrance of an occupied block at said reduced speed, but should a vehicle attempt to enter an occupied block ahead, then the progress of the vehicle towards said occupied block is first automatically stopped, and then the driver or motorman is enabled to again start the vehicle but when progress is resumed the system is such that the speed of the vehicle is automatically cut down to slow speed without any possibility of an increase in such speed so that the vehicle can travel in an occupied track section under conditions assuring a maximum of safety both to the vehicle ahead and to the following vehicle, such progress at slow speed being the only speed at which said following vehicle can proceed within said occupied block or until the entire block is traversed, so that said following vehicle will in due season arrive at or pass one of the magnetic interferences hereinafter described, whereupon the signal indication on the vehicle will have changed from danger to caution, or from caution to clear or the vehicle will have been brought to a full stop, but should the signal indication be changed so as to justify the vehicle proceeding under a clear signal, then the mechanism which limits the vehicle to slow speed or any controlled speed will be automatically cut out of service so that the vehicle may proceed at full speed; further,

provision is made for the display of a signal constantly to the view of the driver and preferably in the cab or motorman's box, the signal so displayed being of a character to denote the condition of the track ahead, thus a clear signal is shown to the driver when there is no vehicle within signalling distance, or should a vehicle occupy the track within a predetermined distance of the following vehicle, then the character of the signal is changed to denote caution, but should the following vehicle approach a vehicle ahead so that a relatively shorter distance separates the two vehicles, then the signal on the following vehicle is changed to denote danger; further, should the signal on a following vehicle change from clear to caution, or from caution to danger, the driver is given an opportunity of manually reducing the speed of said following vehicle, but in the event that the speed is not reduced after the vehicle has proceeded a certain distance subsequent to the change of signals, then means are brought into service whereby the desired speed reduction is effected automatically and the speed of said vehicle cannot be thereafter increased by any effort of the driver, nor can it be increased until the character of the signal changes from caution to clear, or from danger to caution, as circumstances may require; further, in a preferred form, the system makes provision for the vehicle to proceed at variable speeds intermediate full speed and low speed, which variable speeds are automatically regulated and are dependent upon the distance separating the following vehicle from the preceding vehicle.

The system embraces a track equipment and a vehicle equipment mutually cooperating to effect the desired signal and speed control without, however, requiring physical contact between the movable equipment on the vehicle and the stationary track equipment, such freedom from physical contact between the track equipment and the vehicle equipment resulting in an air gap intervening the two said equipments, whereby the liability of disarrangement due to physical contact is wholly obviated and the influence of the track equipment upon the vehicle equip-

- ment is obtained through said intervening air gap and independent of climatic and weather conditions. Furthermore, the vehicle equipment embodies a brake mechanism 5 for effecting the required speed reduction, which brake mechanism is controllable in two respects, one of which is manually operable at the will of the driver and the other of which is wholly automatic, the source of 10 energy for the brake when operated automatically being wholly independent of the source of energy when the brake is manually controlled, as a result of which it is not possible for the driver to interfere in any 15 manner whatsoever with the automatic application of the brake except that the driver may still further apply the brakes so as to make a further speed reduction or to bring the vehicle to a full stop.
- 20 The track equipment is of such a nature that each block or section requires a low consumption of current from a suitable source to maintain each particular block or section in a condition for service, thus obtaining economy in current consumption, but when a particular block or section is occupied by a vehicle, then the full energy from the available source of supply is brought into condition for use automatically, provided, however, that the track ahead is not occupied by a vehicle 25 within signalling distance of the particular block so occupied.
- 30 The track equipment includes, preferably, a closed track circuit for each block, although an open track circuit may be utilized, the closed track circuit being preferred for the reason that should a rail or conductor be broken or a battery be exhausted then the signal on the vehicle is displayed at danger 35 and said vehicle brought to a stop.
- 40 According to this invention, the track equipment for each block or section embodies a relay and a source of direct current energy in a normally closed track circuit the latter 45 including also a high resistance relay, the latter being positioned at or near one end of the block, whereas the first named relay and the energy source are at or near the opposite end of the block, as a result of which organization 50 I am enabled to secure accuracy in the operation of the signals, notwithstanding the equipment may be subjected to the influence of extraneous currents or to the existence of current leakage across the insulations of the 55 sectional track rail or between the parallel rails of the track, and it is possible, also, to install the track equipment utilizing direct current at substantial economy as compared with the cost of equipment dependent for its 60 operation upon the energy of alternating current.

In the drawings

Figure 1 is a diagram illustrating my system of train signal and control, the dotted lines representing a preceding vehicle in one

block and a following vehicle in a certain block to the rear of the preceding vehicle, the devices being shown in their normal positions.

Figure 2 is a sectional elevation, the lower 70 part of the figure illustrating one of the track magnets in elevation and the upper part of the figure showing in section and in elevation a device on a moving vehicle adapted to pass through the magnetic field of the track magnet so as to be influenced thereby in controlling a solenoid for one of the signals, such as the caution signal or the danger signal.

Figure 3 is a horizontal sectional plan view, the plane of the section being indicated by the 80 dotted line 3—3 of Figure 2.

Figure 4 is a view partly in elevation and partly in section of the circuit maker and the magnetic interference, said circuit maker being carried by the moving vehicle, whereas 85 the magnetic interference constitutes a part of the track equipment.

Figure 5 is a sectional plan view of the circuit maker and the magnetic interference, the plane of the section being indicated by the 90 irregular dotted line 5—5 of Figure 4.

Figure 6 is a sectional elevation of the automatic speed governor adapted to be driven by the rotary motion of an axle on one of the moving vehicles, said governor operating 95 primarily to control speed of the moving vehicle when it is within signalling distance of a preceding vehicle.

Figure 7 is a vertical section on the line 7—7 of Figure 6.

Figure 8 is an elevation of a solenoid embodying a retarding device and adapted for use in connection with the caution signal or with the danger signal.

Figure 9 is a vertical section on the line 105 9—9 on Figure 8.

Figure 10 is a horizontal section on the line 10—10 of Figure 8.

Figure 11 is a horizontal section on the line 11—11 of Figure 8.

Figure 12 is a section, partly in elevation, of a valve mechanism associated with the air brake on a moving vehicle, certain parts of said air brake system being illustrated diagrammatically.

Figure 13 is a vertical section of the solenoid which indirectly controls the brake mechanism of Figure 12 and which controls, also, a circuit which includes a vehicle propelling motor.

Figure 14 is a vertical sectional elevation through one of the solenoids connected in series with the rails of one block for controlling the energization of the track magnets of certain blocks in the rear.

Figure 15 is a horizontal section on the line 120 15—15 of Figure 14.

Figure 16 is a vertical section of another solenoid connected across the rails constituting one block so as to be shunted by the 130

presence of a vehicle occupying said block.

Figure 17 is a horizontal section on the line 17—17 of Figure 16.

Figure 18 is a vertical section of a cut out 5 solenoid connected in a shunt around the track-battery of each block.

Figure 19 is a plan view of the cut-out solenoid of Figure 18.

Figure 20 is a diagram of a vehicle equipment for one car of a train adapted to control 10 the entire train from the front end of the leading car when moving in one direction and operating, also, when running in the opposite direction to transfer the signal control to the 15 other end of the train, that is, the car which was previously the leading car now becomes the rear car of the train, and the signal and automatic brake control are automatically changed to the aforesaid leading car.

20 In the system diagrammatically represented in Fig. 1, the track is shown as embodying a continuous rail a and a sectional rail a' , the parts of said sectional rail being electrically insulated at a^2 so as to produce 25 a succession of "blocks" each of any required length, three of said blocks A B C and a part of a fourth block D being represented. Each block is equipped as follows:

At the point where a vehicle enters each 30 block is positioned a solenoid-relay 10, the coil of which is connected directly to the rail a' of said block. A second solenoid 11 is connected also to the rail a' , preferably at or near the point where a vehicle emerges from each 35 block, and from this solenoid 11 a conductor 12 leads to the continuous rail a , and from said rail a leads a conductor 13 to the negative pole of battery 14, from the positive pole of which a conductor 15 leads to the solenoid-relay 10, thus establishing a closed track circuit 40 for the current to flow from battery 14, conductor 15, solenoid-relay 10, rail a' , electrically conductive interference 30, solenoid 11, conductor 12, a part of rail a , conductor 45 13 to the negative pole of battery 14. The two solenoids 10, 11, included in the closed track circuit are energized under normal conditions by current from battery 14, so that with both the coils 10, 11, connected in series with battery 14 as shown, there will be 50 a minimum flow of current through solenoid 10 and said minimum flow of current through said solenoid 10 holds the core thereof normally in a position to complete the circuits 55 through certain track magnets of blocks positioned rearwardly of the particular block as will be presently described. At the same time the coil of solenoid 11 holds the core thereof in a raised position and free from certain contacts in circuits leading to the track 60 magnets of the block with which the solenoid 11 is directly associated. The two solenoids thus perform distinct functions with respect to the block to which said solenoids are connected; thus, solenoid 11 opens and closes the

circuits to the track magnets which are associated with the same block so that said solenoid 11 is a local make and break device for said particular block, thus acting as a local circuit closer, whereas the other solenoid 10 70 is the signal controlling element for the track magnets in blocks positioned rearwardly and for definite distances of the particular block under consideration as is to be shown. It may be stated that with a vehicle present in 75 a particular block, the flow of current from the battery to solenoid 11 is shunted by the wheels and axles across the rails a a' of that block, thus de-energizing the coil of solenoid 11, whereupon the core 11^a drops by gravity 80 and the switch member 11^b of said core makes certain contacts so as to connect the track magnets electrically with the return rail a , as will appear hereinafter.

In this invention there is at all times displayed in the view of the engine driver or motorman a signal of one character or another for indicating the condition of the track ahead; thus, with a clear track for a certain distance or for a certain number of 90 blocks ahead, the signal on an approaching vehicle indicates clear; with a vehicle in a block a certain distance ahead the signal on the approaching vehicle is changed automatically to cut out the clear signal and to 95 display caution signal when the following vehicle reaches a certain distance in the rear of a preceding vehicle, but with the following vehicle proceeding to a point still closer to the preceding vehicle, then the signal is 100 once more changed on the following vehicle so as to cut out the caution signal and to display a danger signal. The territory thus protected by signals comprises what may be termed a "control zone", in that the cab 105 signals for this territory together with the automatic braking provided for is under the control of track conditions in the advance zone of similar characteristics. Such a zone for example is illustrated in Fig. 1 by the 110 adjacent blocks C, B.

To the attainment of these ends, it is preferred to equip each block with two rows of magnets adapted to be so controlled as to influence the vehicle equipment for the display of signals according to the condition of the track and to the distance separating a following vehicle from a preceding vehicle. The number and arrangement of the track 115 magnets in each block is dependent in a certain measure upon the proximity or remoteness of the particular block from a "point of congestion," so called, by which term is meant any condition of the track at which trains may be likely to congregate or to stop, such e. g. as a station, either for express 120 trains or local trains, a switch or a crossover, or a curve in the track. Thus in blocks remote to the point of congestion, the number of track magnets may be at a minimum, say 125 130

two in a row, whereas in blocks closer to the point of congestion, the track magnets in each of two rows are increased in number so as to actuate the cab signal control mechanism an increasing number of times the nearer the vehicle approaches the point of congestion.

A salient feature of this invention is the provision of means for automatically controlling the speed of a vehicle so that it is reduced without any effort upon the part of the driver; in fact, is not within the driver's control. Briefly, the signals displayed in the cab are dependent upon the condition of the track, whereas the speed of the vehicle is dependent upon the signals displayed in the cab.

With each block A B C D etc. there are associated two rows of track magnets, the magnets of the one row being indicated at 16 and the magnets of the other row at 17, said magnets 16, 17, operating to control the caution signal and the danger signal, respectively, but the influence of the track magnets upon the equipment carried by a following vehicle is dependent upon the condition of the preceding blocks controlled through the solenoids 10 as will hereinafter be shown. As shown, each solenoid 10 includes a plunger or core 18 provided with wiping contacts 19, 20, 21 electrically insulated at 22 and cooperating with the circuit contacts positioned intermediate the conductors leading from the battery 14 to the track magnets in a certain number of blocks positioned in the rear of the particular block adapted to be occupied by a vehicle, the arrangement being such as to bring about the following results; with a particular block occupied by a vehicle, the current from battery 14 associated with that block is shunted out of the circuit closing solenoid 11 by the wheels and axle across the rails *a a'* so as to establish an increased flow of current in the controlling solenoid 10, thus moving the core 18 and shifting the contacts 19, 20, 21, to interrupt the circuits as follows:—first, to the magnets 17 of the first block i. e. the block immediately in the rear of the occupied block as well as the last magnet 17 at the exit of the second block in the rear; second, to interrupt all the magnets 16 in the first and second blocks in the rear, and, third, the circuit to the last magnet 16 in the third block in the rear. It is thus apparent that, under the conditions recited, the solenoid 10 performs certain important functions in interrupting the circuits to the magnets 17 positioned in the first and second blocks in the rear for influencing the danger signal and, also, interrupts the circuits to the magnets 16 in the second and third blocks in the rear to influence the caution signal, whereby there may be said to be an overlap in the relation to each other of the caution and danger con-

trolling magnets in the second and third blocks in the rear. Thus in respect to the control zone above referred to the said last magnet 16 at the exit of the third block to the rear when deenergized collaborates with other instrumentalities later to be referred to, to effect the display of a caution signal at the entrance to the protected control zone, and the said magnet 17 at the exit of the second block to the rear when deenergized and with like collaboration effects the display of a danger signal at an intermediate point in the said protected control zone.

It is preferred to wire the magnets as follows:—

From the battery conductor 15 a lead 23 runs to contact 19 of the first solenoid 10, thence it runs at 23^a to the magnets 17 of the first block in the rear; thence at 23^b to the last magnet 17 of the second block in the rear and thence at 23^b to the magnets 16 (one or more) of the second block in the rear; thence to contact 21 of the third solenoid 10, thence at 23^c to the last magnet 16 of the third block in the rear, thus constituting a continuous lead from battery 14 of one block to as many blocks in the rear as it may be desired to control the signals; thus, the signal control herein shown extends rearwardly through three blocks from an occupied block and spans the control zone as above explained. It is apparent that said conductor 23, 23^a, 23^b, 23^c is in effect a continuous conductor from the positive side of the battery 14 of one block to the specified magnets 16, 17 of three blocks in the rear. When this circuit is broken by relay 10 by reason of the presence of a train as indicated by the trucks X, for example, in block A, which comprises the first half of the advance control zone, provision is made for the caution signal at the entrance to the control zone C, B, and the danger signal intermediate said control zone (C, B) as above pointed out. With the track clear and under normal conditions, the flow of current from battery 14 of one block to certain track magnets in three blocks in the rear is interrupted because the solenoid 11 of each block is energized under said normal conditions to break the return connections from the specified magnets to the battery 14.

The track magnets under normal conditions are thus de-energized and the circuits from the battery to the magnets are open; this is considered advantageous for the reasons that economy of current is obtained and by energizing the magnets intermittently, instead of continuously, it is possible to so wind them as to obtain an increased magnetic pull between the magnets and the elements of the vehicle equipment.

The preceding detailed description sets forth the circuit connections from the positive side of a battery in one block, to the magnets 16, 17 of three blocks in the rear, 130

under normal conditions, and it is now desired to explain the manner of obtaining the return connections from the specified magnets to the negative side of the battery when the particular block is occupied, normal conditions prevailing, and with a clear track ahead of the occupied block. In this connection it is proper to say that the return connections of one block are the same as similar connections for every other block of the system, and that the electrically continuous rail *a* or the ground is utilized as a common return. The return circuit connections of each block include the circuit closing solenoid 11, the moving part 11^b of which is adapted to make electrical connection with a group of contacts 24; from one contact 24 a conductor 25 leads to the final magnet 17 of the block; from another contact leads a conductor 26 to the remainder of the magnets 17 in said block; from another contact 24 a conductor 28 leads to the remainder of the magnets 16 in said block, and from the last contact 24 a conductor 29 is branched onto conductor 12 leading to the return rail *a* or the ground. With the solenoid 11 de-energized by the presence of a vehicle in a particular block, the core or plunger 11^a drops for member 11^b to make electrical connection with one group of contacts 24, and thus all the return connections are completed from the magnets 16, 17 of a particular block to the return rail *a* or the ground leading to the respective batteries 14 in the blocks preceding the occupied blocks with which said magnets are associated.

The track magnets 16, 17, in the series of blocks and energized by current from the batteries 14 as described, produce in the track a magnetic circuit or means possessing magnetic permeability, the fields of which magnets emanate lines of force so as to influence the armatures on the vehicle equipment passing through said fields, said armatures of the vehicle equipment and the track magnets being free from physical contact and being separated by an air gap, as before explained. When the track is unoccupied, the magnetic field produced by the track magnets in the successive blocks is of a desired length suited to the conditions of vehicular traffic, but the presence of vehicles on the track and the proximity of such vehicles to each other produces automatically a change or variation in the operative length of the track circuit. The presence of vehicle X in block A shunts current from solenoid 11 by the wheels and axles of said vehicle X in contact with the rails, and this influences solenoid 10 so that the latter interrupts the circuit to track magnets 17 of the first block in the rear of the occupied block and also the first magnet 17 at the exit of the second block in the rear,

and at the same time the solenoid 10 interrupts all the magnets 16, in the first and second blocks in the rear of the occupied block, and also interrupts the last magnet 16 in the third block in the rear of said occupied block. 70

The solenoids 10, 11, cooperate to effect a variation in the length of the magnetic track circuit, and such operative length of the magnetic track circuit is dependent upon the distance intervening the two vehicles upon the track, one of which vehicles precedes the other within a determined distance, for the reason that the following vehicle moving in a block or blocks in rear of the occupied block so influences the solenoids 11 of the 75 blocks that on the continued forward movement of said following vehicle the solenoids 10 are in like manner successively influenced and thus reduce the operative length of the 80 magnetic circuit afforded by the track magnets according to, and in proportion to, a decrease in the distance separating the two 85 vehicles.

Further, the magnetic circuit in the track is formed by two series of track magnets 16, 90 17 in the successive blocks, one series of magnets, as 16, in the successive blocks may be in service or de-energized dependent upon the proximity of the two vehicles so that the magnetic circuit formed by the magnets 16 95 is of a certain length, whereas the magnetic circuit formed by the other series of track magnets 17 in successive blocks may be in service or de-energized according to the proximity of the two vehicles so as to result in a 100 magnetic circuit also of a desired length, which two magnetic circuits formed by the two series of magnets 16, 17 and their complementary solenoids and batteries are, or may be in overlapping relation to each other so 105 as to effect the control of the signals and the brake mechanism of the vehicle equipment in a desired order.

It is understood, furthermore, that the track circuit is grounded by the presence of 110 rolling stock, such as a vehicle Y or Z upon the rails *a*, *a'* and within a given block or blocks thereof, said track circuit or magnetic circuit including stationary magnets 16 or 17, or 16 and 17, extending in series substantially throughout a different block or blocks from that in which the ground may be effected. Said track magnets emanate lines of force and constitute a magnetic field through which are adapted to travel certain 115 elements, as 16^a, 17^a and 47^a, of an equipment on a moving vehicle, which elements are included in a circuit or circuits of said vehicle equipment.

Again, the solenoid 10 is so connected in 120 circuit with the track magnets as to normally de-energize the latter, but the solenoid 11 is influenced by the presence of a vehicle on the track so that it shunts current through the solenoid 10 and simultaneously therewith es- 130

tablishes the magnetic field of said track magnets.

In addition to the track magnets, 16, 17, the solenoids 10, 11, and the other devices heretofore described, each block is equipped with means for interrupting electrical circuits in the vehicle equipment, said circuit interrupting means being positioned adjacent to or at a suitable distance from the point 10 at which a vehicle leaves the block. Various forms of the circuit interrupting devices may be employed, but as shown this part is a magnetic interference occupying such position in the track that as a vehicle passes the device 15 the latter is interposed in the magnetic field of a certain magnet on the vehicle so as to shunt the field of said magnet and thereby change the signals should the condition of the track warrant such change or to operate the brake 20 control to a full stop should the track conditions justify the same. The magnetic interference is in the form of a metallic bar, 30 preferably of magnetizable soft iron extending upwardly from the track near one of the 25 rails, said bar being electrically connected with the rail α' , so as to be in circuit therewith. Should it happen that in the course of repairing the track, the workman omits to replace the magnetic interference 30, provision 30 is made for interrupting the circuit through rail α' by dividing and insulating the rail at α^3 at a suitable distance from the exit of the block, said interference 30 being bonded to the rail α' in any suitable way so as to render the rail α' electrically continuous 35 around the break α^3 .

As is well known, service of the battery 14 occasions diminished energy, but to provide a margin of safety in maintaining each 40 block in a serviceable condition, means are employed to interrupt the local track circuit through solenoids 10, 11 of said block when the battery reaches a certain minimum strength. Accordingly, a cut out 31 is interposed in the battery circuit, said cut out 45 including a coil connected in a shunt around the battery and the core or plunger of said coil controls a trip 32.

The coil of the cut-out is wound to a certain resistance, and when current from the battery becomes weakened to a point where the coil is not sufficiently energized to overcome the action of a mechanical retractor 55 included as a part of the cut-out, then the core or plunger is actuated to operate the trip and thus break the battery circuit for the particular block with which the battery is connected, as will appear more fully in 60 connection with one detailed form of the cut-out hereinafter described.

The vehicle equipment includes signals 33, 34, 35 indicating clear, caution and danger respectively, energized from a common battery 65 36, or other source of electrical energy.

There is a direct lead 37 from the negative side of the battery to the signals, said lead including a suitable resistance 38. All the signals are under the control, primarily, of solenoids 39, 40, the latter being controlled 70 by armatures 16^a 17^a carried on the vehicle and by the signal-circuit maker 47, said armatures being in turn controlled by the track magnets 16, 17 of the track equipment.

Solenoid 39 is shown as a coil and a 75 plunger, the latter being equipped with a moving part 39^a which carries a plurality of switch members 41, 42, electrically insulated therefrom. In a similar manner, solenoid 40 is a coil and a plunger, the latter having a 80 moving part 40^a carrying switch members 43, 44, also electrically insulated from the core or plunger.

The armatures 16^a 17^a which cooperate with the track magnets have attached thereto 85 switch members 45, 46, respectively.

The circuit maker 47 is shown as a magnet the coils of which are at all times in the circuit of the battery 36, said magnet 47 controlling the armature 47^a, the function of which is to bridge certain contacts and to connect the positive side of battery 36 with the solenoid coils 39, 40, and other elements 90 of the vehicle equipment under certain conditions of operation.

The signal circuits are as follows:—

For the clear signal 33 the circuit includes a conductor 48 extending from the positive side of battery 36 to the switch member 43 of solenoid 40; from said switch member 43 a conductor 49 leads to switch member 41 of solenoid 39, and from the switch member 41 a conductor 50 leads to the lamp denoting clear signal 33. For the caution signal 34, the circuit includes conductor 48, switch member 43, conductor 49, and when the armature 39^a of solenoid 39 is dropped, the conductor 49 to a conductor 51 leading the lamp of caution signal 34. The circuit for danger signal 35 includes conductor 48 to which is connected a conductor 52, and when the armature 40^a of solenoid 40 is dropped, the switch member 44 of said armature bridges the gap between conductors 52, 53, the latter leading to signal lamp 35.

Under normal conditions there is displayed a clear signal by current from battery 36 flowing through lamp 33. To this end, the circuit maker 47 is energized by current from battery 36 flowing through branch conductors 48^a and 37^a to the coils of said circuit maker, whereby the armature 47^a is attracted to close the following circuits:—A branch 48^b is tapped onto conductor 48^a and leads to armature 47^a; from the armature 47^a conductors 54, 55, lead respectively to switch member 42 of solenoid 39 and to switch member 44 of solenoid 40; from switch member 42 a short conductor 56 leads to the coil of solenoid 39, and from 120 125 130

this coil another short conductor 37^b is branched onto the return connection 37 running to the negative side of the battery; from the switch member 44 a short conductor 57 leads to the coil of solenoid 40, from which coil leads a short conductor 37^c branched on the return battery connection 37; to conductor 56 is tapped a conductor 58 leading to the switch member 45 of armature 16^a; and from this switch member 45, a conductor 60 extends to switch member 46, from which member 46 a conductor 59 leads to and is connected with conductor 57 of solenoid coil 40, and connected with said conductor 60 at a point intermediate the switch members 45, 46, is a conductor 61 leading to branch conductor 48^a, thence to conductor 48 and thence to positive side of the battery 36.

As heretofore stated, the clear signal 33 is normally displayed with a clear track ahead of the vehicle carrying the signal equipment. This is due to circuit maker 47 holding the armature 47^a to close the circuit between battery 36 and solenoids 39 and 40 which in turn complete the circuit between battery 36 and lamp 33, the current flowing as follows:—from battery 36, conductor 48, switch member 43 of solenoid 40, conductor 49, switch member 41, conductor 50, lamp 33, and conductor 37, through resistance 38 back to battery. As will be noted the solenoids 39, 40, hold their cores in raised positions for the members 41, 43 to close the signal circuit.

It should be stated that when no vehicle is present in a block, the magnets 16, 17 of that block are de-energized because solenoid 11 of that block is energized so as to hold armature 11^b away from contacts 24, thus opening the circuits to the magnets 16, 17 of each unoccupied block; but as a vehicle Y equipped as described moves along the track and the armatures 16^a 17^a are brought within the fields of the magnets 16, 17, said armatures 16^a 17^a are moved by the magnetic pull of said magnets 16, 17, in the event of the magnets being energized by current from the batteries 14 in the proper blocks of the track ahead of said moving vehicle, Y. Assuming that normal conditions prevail, that the track ahead is clear, and that the vehicle Y is traveling in block D toward the right with a clear signal displayed, the action is as follows:—The wheels and axles of the vehicle Y shunt the current out of solenoid 11, allowing armature 11^b to drop against contacts 24 of the particular block occupied by the vehicle Y. This armature thus completes the return connection from magnets 16, 17 of the occupied block to the batteries 14 of block A and block B respectively, as follows:—With vehicle Y in block D the last magnet 16 of said block D opposite interference 30 is energized by current flowing from battery 14 of block A through conductor 15, switch member 32 of cut-out 31, conductor 23, switch member 19 of

solenoid 10 in block A, conductor 23^a, switch member 20 of solenoid 10 in block B, conductor 23^b, switch member 21 of solenoid 10 in block C, conductor 23^c, magnet 16 in block D, conductor 27 in block D to armature 70 11^b in solenoid 11 block D, conductor 29 of block D tapped onto conductor 12 to return rail *a* and thence to conductor 13 to battery 14 of block A. Last magnet 17 of block D opposite the said interference 30 is at the 75 same time and under the same conditions energized as follows:—From battery 14 of block B current flows through conductor 15, switch member 32 of cut-out 31 in block B, switch member 19 of solenoid 10 in block B, 80 conductor 23^a, switch member 20 of solenoid 10 in block C, conductor 23^b, to magnet 17 in block D, thence by the return connections including conductor 25 block D, switch member 11^b of solenoid 11 block D, conductor 29 tapped on conductor 12 block D, thence by return rail *a* to conductor 13 block B, to battery 14 in the latter block. The magnets 16 and 17 at the rear of block D immediately behind the magnets 16 and 17 90 opposite the interference 30 have their circuits under the control respectively of blocks B and C of the protected control zone shown in Fig. 1 as is apparent from the drawing. For these magnets 16 and 17 to be energized, 95 therefore, it is necessary that the said protected control zone be clear. As will later appear more fully, these magnets 16 and 17 at the rear of block D immediately behind the interference 30 act as a resetting means for certain train-carried equipment including the solenoids 39 and 40 respectively. For the said track magnets thus to function the forward train X must have proceeded in its travel out of the protected control zone C, 100 B and into the advance control zone, for example, as shown in Fig. 1.

As the vehicle nears the exit from a block, the armatures 16^a 17^a pass through the magnetic fields of track magnets 16 17, and at 110 the same time the circuit maker 47 assumes such relation to the magnetic interrupter 30 that the latter is brought into the magnetic field of said circuit maker 47. These operations have no apparent effect upon the clear signal 33 should the track ahead be clear and the signal system be in normal condition.

Assuming that a vehicle X occupies the block A and that a vehicle Y with a clear signal displayed is approaching the exit 120 point of block D, a change of the signal indication from clear to caution is effected on said vehicle Y when it passes the magnetic interrupter 30 and the magnets 16, 17 nearest the exit of said block D. This change of signal is brought about by the vehicle X in block A shunting the current in the manner heretofore described so as to interrupt the flow of current from battery 14 of block A to the track magnet 16 of block D, hence as the 125 130

armature 16^a on the vehicle Y passes the de-energized magnet 16 of block D said armature 16^a will remain in its normal position, i. e., it will not be influenced by a magnetic pull from said magnet 16. When the circuit maker 47 of the vehicle Y is passing the interference 30 in block D, the armature 47^a will not be attracted for an appreciable interval of time because of the presence of the interference 30 between the armature 47^a and the poles of the magnet 47, and thus a spring 47^b pulls the armature 47^a away from the poles of the magnet so as to break the circuit between the battery 36 and solenoids 39, 40, 10 but the armature 17^a is attracted by the track magnet 17 so as to complete the circuit from battery 36 direct to coil of solenoid 40 during the interval of interruption of circuit maker 47 by the interrupter 30, at which period the solenoid 39 is de-energized, permitting armature 39^a to drop, interrupting the flow of current to clear signal 33 and establishing the flow of current from battery 36 to caution signal 34. As the vehicle passes the interference 30 in block D, and immediately thereafter the magnetic pull of magnet 47 attracts armature 47^a so as to close the battery circuit to the switch member 44, and solenoid 40 remains energized until the next interruption, 20 the solenoid 39 being de-energized at this time because the battery circuit to signal solenoid 39 is interrupted at switch member 42, and solenoid 39 remains de-energized until the vehicle Y progresses sufficiently to bring the armature 16^a within the field of an energized track magnet 16 however far said energized magnet 16 may be located from the track magnet at which the signal changes take place. Assuming that vehicle X remains in block A, the vehicle Y now passes into block C, and is free to proceed therein until it reaches the interference 30 of said block C without any change of signal indication, caution signal being constantly displayed because magnets 16 of block C are de-energized. As the vehicle Y passes over the final magnets 16, 17 of block C and the interference 30 of said block, C, the said interference is interposed between the armature 47^a and the poles of circuit maker 47 so as to interrupt the circuit from battery 36 to switch member 44 and solenoid 40, and as the armature 17^a of said vehicle Y passes over a de-energized magnet 17 in block C, at the same instant that the circuit maker 47 interrupts the circuit it follows that the armature 17^a is not attracted by said de-energized magnet 17 of block C, hence armature 40^a is dropped and the circuit to battery 36 is opened at switch member 43 to both the clear and caution signals 33, 34, and current is directed by switch member 44 to flow through the danger signal 35.

The danger signal is thus displayed in vehicle Y so that Y must by the operation of a

brake mechanism to be hereinafter described come to a stop in block B and remain in said block B or near the end thereof next to interference 30 in said block B, this condition prevailing until a change takes place in block A. As X moves out of block A and into the next preceding block, the magnets 17 of block B become energized and the armature 17^a is attracted so as to complete the circuit from battery 36 to the coil of solenoid 40, thus cutting out the danger signal and displaying the caution signal. With block A vacated by the forward movement of vehicle X into the block next ahead, or as it may be referred to, the next preceding block, vehicle Y with the caution signal displayed is free to move into block A, but when X moves into the second block ahead and with Y in block B, then the signal indication of Y is changed from caution to clear.

It will be noted that the magnets 16, 17 of the track equipment and the armature 16^a, 17^a and 47^a of the magnets in the vehicle equipment are free from physical contact, an air gap intervening between the armatures on the vehicle equipment and said track magnets and the magnetic interference when the vehicle travels on the track in proximity to said track magnets and the magnetic interference.

I will now proceed to describe the mechanism whereby the speed of a vehicle moving within blocks at predetermined distances in the rear of an occupied block is automatically reduced. Each vehicle is equipped with a speed governor 65 of any suitable type adapted to be driven from an axle of said vehicle, said governor operating directly on a switch 66 adapted to make electrical connection with the series of contacts 67, 68, 69, 70, 71, whereof the contact 67 is directly connected, by a conductor 67^a branched on to the lead 48, with the positive side of battery 36, it being noted that the contacts vary in length and that at all speeds in excess of the predetermined speed permissible with the caution signal displayed the switch member 66 is free from engagement with all the contacts of the group enumerated.

I desire to state, prior to a detailed explanation, and to have it understood now, that the reduction of speed of the moving vehicle is to be effected by the application of a brake to the vehicle and by shutting off the power, to which ends I employ a solenoid 72 which acts primarily to open and close the circuit from battery 36 to air-brake-control relay 73 and to cut off the power normally supplied to the controller 74. As is usual in the art, electric power is supplied from a third rail or otherwise to a motor 75 for propelling the vehicle, said motor being connected in circuit with the controller in the usual way, and the leads 76, 77, of said circuit for the motor and the controller extending to

a switch member 78 movable with, and insulated from, the armature 72^a attached to the plunger or core of said solenoid 72. The air-brake-control relay 73 will be described in detail hereafter, but as shown by the diagram the coil of said relay is in a circuit formed by leads 80, 81, said lead 80 extending directly to the switch member 79 movable with and insulated from the armature of the solenoid 72 whereas the lead 81 extends from said switch member 79 to and is tapped onto the conductor 48 to the positive side of battery 36, the return from relay 73 to the negative side of battery 36 being through conductors 82, 83, the latter being tapped onto conductor 37^a.

The solenoid 72 which directly influences the brake relay 73 and the controller circuit is energized by current from battery 36 when the signal control solenoids 39, 40, are effective in displaying a clear signal and with the speed governor switch 66 free from the contacts aforesaid; but cooperating with the solenoid 72 are two other solenoids 84, 85, which under certain conditions open and close the circuits from battery 36 to solenoid 72. For the purpose of distinguishing solenoid 84 from the other solenoids it will be hereafter designated as the full stop solenoid; the solenoid 85 as the low speed solenoid, and the solenoid 72 as the brake and controller solenoid.

As shown, the armature 84^a of full stop solenoid 84 is equipped with switch members 86, 87, insulated from said armature, whereas the low speed solenoid 85 has its armature 85^a equipped with other switch members 88, 89, electrically insulated from said armature.

Before describing the circuit connections for the solenoids 72, 84, 85, it is desired to state that the signal controlling solenoids 39, 40 are constructed with retarding devices, preferably in the nature of dash pots as will be hereafter fully described, for the purpose of delaying the automatic application of the brakes and the shutting off the power so that the driver is given an opportunity, after a change of signal as from clear to caution or from caution to danger, to manually apply the brakes and to shut off the power in order to effect the required speed reduction, but should the driver neglect to perform these functions manually, then after an appreciable interval the speed control mechanisms in their entirety act automatically either to reduce the speed within appropriate limits or to bring the vehicle to a full stop as will be hereinafter described. It will be seen that the signal control solenoid 39 is equipped with a switch member 90, operated by and insulated from the retarding mechanism of said solenoid 39, whereas with the other signal control solenoid 40 there are associated two switch members 91, 92, operated by and insulated from the retarding devices connected with said solenoid 40.

With a vehicle in which a clear signal is displayed, moving at a higher speed than is permissible should the caution signal be displayed, the speed governor switch 66 will be free from the contacts composing the group, 78 the low speed solenoid 85 is de-energized, full stop solenoid 84 is energized, and the brake and controller solenoid 72 is energized, the circuit connections being as follows:—From the coil of solenoid 72 a conductor 94 leads to switch member of solenoid 85 in either of the two positions of armature 85^a; from switch member 88 a conductor 96 leads to switch member 87 of solenoid 84; from switch member 87 a conductor 97 leads to and taps onto conductor 98 leading to switch member 91 of solenoid 40; from switch member 91 a conductor 99 leads to and is tapped onto conductor 100, the latter leading to switch member 90 of solenoid 39; from member 90 a conductor 101 leads to switch member 92 of solenoid 40; a conductor 102 is tapped onto conductor 101 intermediate the switch members 90, 92, and said conductor 102 is tapped onto conductor 61 leading to positive side of the battery 36; the described connections completing that part of the circuit between the coil of solenoid 72 and the positive pole of said battery. The connections between the solenoid coil 72 and the negative pole of the battery 36 are constituted by a conductor 103 leading from the coil 72 to the coil of solenoid 84; tapped onto conductor 103 is a conductor 104 which is tapped onto conductor 83 and thence to the negative pole of said battery.

From the coil of solenoid 84 leads a conductor 105, branched for one part to extend to switch member 92 and the other part to switch member 86 forming part of the circuit of relay 84; from switch member 92 leads the described conductor 101, thence to conductor 102 leading as stated to the positive pole of battery 36. As shown, there is another connection whereby the coil of solenoid 84 is in communication with the positive side of the battery as follows:—From switch member 86 of solenoid 84 a conductor 106 leads to the armature 47^a of circuit maker 47 and thence by conductors 48^b, 48^a and 48 to the positive side of the battery. The negative connections of solenoid coil 84 with the battery are through conductors 103, 104, 83, 37^a and 37.

Ordinarily the low speed solenoid 85 is de-energized, but the coil thereof has a direct connection through conductor 83 with the negative side of the battery 36. When energized, the coil of solenoid 85 is connected with the positive side of said battery as follows:—Conductor 110 which is branched for one branch thereof to have contact with switch member 89 when armature 85^a is attracted whereas the other branch of said conductor 110 leads to a contact in the

path of switch member 87 of solenoid 84, so as to make electrical connection with said member 87 when the armature 84^a is dropped; in this position of armature 84^a conductor 108 is also in contact with switch member 87, said conductor 108 leading to contact 68 of the speed governor, said speed governor contact 68 being of such a length that the vehicle must come to a full stop before the governor switch 66 will bridge the gap between governor contacts 68, 67; from contact 67 the conductor 67^a leads to conductor 48 to positive pole of the battery 36.

The operation of the speed control mechanism in applying the brakes and shutting off the power is dependent in a measure upon the signal solenoids, and upon the neglect or refusal of the driver, when the signal changes, to make a proper speed reduction. Accordingly, the signal solenoids 39, 40, are connected indirectly with the governor contacts 70, 71 as follows:—From contact 71 the conductor 100 leads to switch member 90 of solenoid 39. From contact 70 conductor 98 leads to switch member 91 of solenoid 40.

The operation of the speed reducing mechanism is as follows:—With a vehicle Y moving in, say, block D with a clear signal and at any speed in excess of the predetermined speed permitted when the caution signal is displayed, the governor 65 is driven and holds the switch 66 free from all the governor contacts. Assuming that block A is occupied by vehicle X and that vehicle Y is passing over the last magnets 16, 17 and interference 30 of block D as shown, it follows that the signal changes from clear to caution as heretofore described, the armature 39^a of solenoid 39 drops and permits a retarding device associated with said solenoid 39 to act in a manner hereinafter described to effect a relatively slow movement of switch member 90, thus giving the driver sufficient time to apply the brakes and effect the required reduction in speed before the circuits are interrupted by switch member 90, thus resulting in a corresponding collapse of the speed governor 65 and a movement of the switch 66 into electrical engagement with contacts 71 and 67, the speed controlling mechanism herein disclosed permitting of the usual manual application of the brakes independently of the automatic action of the speed controlling mechanism itself. Should the engine driver neglect or refuse to manually reduce the speed, then the operation of dropping armature 39^a associated with solenoid 39 allows the retarding device of said solenoid to drop, after a short interval of time, the switch member 90 and thus interrupt the circuit between solenoid 72 and the positive side of battery 36, permitting armature 72^a of solenoid 72 to drop and interrupt also the circuit connecting the brake solenoid 73 and the battery, and also to break the circuit including the

controller and motor, thereby shutting off the power and applying the brakes automatically to effect the required speed reduction. When the brakes are applied, vehicle Y will have passed into block C, and when the required speed reduction is made the governor 65 shifts the switch 66 into electrical engagement with contacts 67, 71, the effect of which is to restore the connection from the positive side of battery 36 with solenoid 72 as follows:—Current flows from positive battery through conductors 48, 67^a to contact 67, governor switch 66, contact 71, conductor 100, conductor 99, switch member 91 of solenoid 40, conductor 98, conductor 97, switch member 87, conductor 96, switch member 88 of solenoid 85, conductor 94, solenoid 72, and thence through conductors 103, 104, 83, 37^a and 37 to negative side of battery. Solenoid 72 is thus energized and armature 72^a attracted so as to restore normal condition to the brake solenoid 73 and to complete the power circuit.

Vehicle Y can now proceed, with caution signal displayed and under a certain predetermined speed, through block C and into block B, but with vehicle X still in block A, the signal indication on vehicle Y is again changed when passing over interference 30 of block C so as to cut out the caution signal and display the danger signal. This change of signals is due to the dropping of armature 40^a of solenoid 40 as described heretofore, the core and retarding device of said solenoid 40 giving ample opportunity for the engine driver to effect a still further reduction of speed manually, which speed reduction actuates the governor 65 to move the governor switch 66 into engagement with contacts 67 and 70. Should the engine driver not exercise this precaution, the switch member 91 of said solenoid 40 opens the circuit previously established by the speed reduction mechanisms automatically brought about when the signal changed from clear to caution, and thus the connection from positive battery to the solenoid 72 is again interrupted, this time by switch member 91 of solenoid 40, de-energizing the solenoid 72 and armature 72^a drops to apply the brakes and shut off the power. The proper reduction having been made in the speed of vehicle Y, the solenoid 72 is again energized as follows:—from positive battery through leads 48, 67^a, contact 67, governor switch 66, contact 70, conductors 98, 97 switch member 87 of solenoid 84, conductor 96, switch member 88 of solenoid 85, conductor 94, solenoid 72, the return from solenoid 72 being by conductors 103, 104, 83 37^a, 37 and negative battery. Solenoid 72 is thus re-energized to restore normal conditions to brake solenoid 73 and the motor circuit.

It is apparent that should the vehicle Y proceed at a speed exceeding that permissible

5 by the respective signals, the speed governor 65 will be operated to interrupt the circuit required to energize solenoid 72, and thus the speed will be reduced automatically to that in correspondence with the signal condition.

10 With block A still occupied by vehicle X, vehicle Y can proceed, with the danger signal displayed and at the properly reduced speed, to move through block B up to the interference 30, at which a visual marker may be employed for the guidance of the driver. With the danger signal displayed, it is apparent that the engine driver should manually bring the vehicle Y to a full stop in 15 block B just before reaching interference 30, in which position the armatures 16^a 17^a will be over the magnets 16, 17, second from the exit point of block B. Vehicle Y should remain at a full stop in the last described position until vehicle X moves out of block A 20 when magnet 17 will be energized. This will in turn attract armature 17^a on vehicle Y and will change signal from danger to caution, it being obvious that a vehicle should not pass 25 the interference 30 with a danger signal showing. In this connection it should be observed that the interference 30 should be spaced far enough from the exit of each 30 block to permit the automatic stop mechanism to bring the vehicle to a full stop from the maximum speed permitted by the speed control mechanism when the danger signal is displayed. It is evident that the minimum length of any two adjoining blocks is determined by the distance required for the engineer to first reduce the speed and, second, to 35 bring the vehicle to a full stop should the signal conditions require the same.

40 With vehicle X still in block A and vehicle Y in block B, should an attempt be made by vehicle Y to pass interference 30 in block B, then the brakes are automatically applied to vehicle Y for bringing it to a full stop as follows:—As the circuit maker 47 of 45 vehicle Y passes the interference 30 in block B, the said interference interrupts the magnetic circuits of 47 as described and armature 47^a breaks the circuit from battery 36 to solenoid 84, whereupon armature 84^a drops 50 to open the circuit from battery 36 to solenoid 72, thus applying the brakes and cutting off the power, as a result of which the vehicle is brought to a full stop before vehicle Y can pass out of block B. At this time the 55 switch member 87 of solenoid 84 connects the coil of solenoid 85 with the governor contact 68, whereupon the stopping of the vehicle causes the governor 65 to shift switch 66 into engagement with contacts 68, 67, so 60 that the coil of solenoid 85 is energized by current flowing from positive battery, conductors 48, 67^a, governor contact 67, governor switch 66, contact 68, conductor 108, switch member 87 of solenoid 84, conductor 110, 65 coil of solenoid 85, thence through con-

ductors 83, 37^a, 37, to negative battery. This attracts armature 85^a which bridges the gap between conductor 110 of coil 85 and a conductor 115 leading to a contact in the path of armature 47^a of the 70 circuit maker 47, thence to positive pole of battery 36, thus completing the circuit of solenoid 85 as follows: From the positive side of battery 36, through conductors 48 and 48^a, armature 47, conductor 115, switch member 75 89, conductor 110, solenoid 85, back to the negative side of the battery.

The solenoid 84 is again re-energized when upon passage of an energized magnet 17, solenoid 40 is re-energized. The pick-up circuit of solenoid 84 is then established as follows: From the positive side of battery 36, through conductors 48, 61 and 102, through switch member 92 of solenoid 40, conductor 105, solenoid 84, back to the negative side of 85 the battery.

With vehicle Y at a full stop at the end of block B, and with solenoid 85 energized, it is apparent that it will remain in such energized condition until vehicle Y again passes 90 one of the interferences 30 in either a preceding block or a succeeding block. It is apparent, also, that with solenoid 85 energized as stated, the armature 85^a is attracted 95 by solenoid 85 and switch member 88 bridges the gap between conductors 94 and 109, thus resulting in solenoid 72 being energized from battery 36 as follows:—Battery 36, conductors 48, 67^a, contact 67, switch 6, contact 69, conductor 109, switch member 88 of 100 solenoid 85, conductor 94, solenoid 72, and thence to negative side of battery by conductors 103, 104, 83, 37^a and 37. The brakes are 105 thus released and the motor circuit restored, the brakes being released so long as switch 66 is in contact with contacts 69, 67, the length of contact 69 relative to contact 67 being such that the switch 66 will bridge said contacts only when the vehicle proceeds at slow speed, but should the speed exceed the 110 predetermined slow speed then the governor will move the switch 66 to break the contacts and again apply the brakes. Accordingly, vehicle Y can proceed at slow speed only from block B into occupied block A, the danger signal being constantly displayed. Should the vehicle X move out of block A into the 115 next preceding block ahead, vehicle Y cannot proceed in block A at a speed in excess of the required slow speed until said vehicle Y passes the interference 30 in block A, notwithstanding the signal conditions may change, and such signal conditions must change from danger to caution or clear, otherwise the vehicle Y will again be brought 120 to a full stop upon passing interference 30 of block A, in which event the interference 30 operates on the circuit maker 47 as described to interrupt the circuit from battery 36 to the coil of solenoid 85, dropping the 130

armature 85^a, thus cutting out the slow speed control by interrupting the required circuits and cuts the speed control mechanism into service as required by the signal indications.

5 Briefly stated, the speed of a follower vehicle while approaching a preceding vehicle is reduced proportionately to the distance separating the two said vehicles; thus, with vehicle X in block A and with vehicle Y 10 traveling in block D, the latter vehicle Y can proceed at any speed desired, but when Y enters block C and thereby approaches closer to X, then the speed of Y while traveling in block C is reduced, and, further, as said vehicle Y moves still closer to X, during which still closer approach, Y travels in block B, then the speed of Y while moving in block B is still further reduced, all of which progressive speed reductions are effected by automatic mechanism, although the system is 20 such that the speed reductions may be effected by manual control of the brake mechanism upon signal to the engine driver.

In Figures 2 to 19 inclusive there are illustrated 25 various constructional forms of the devices employed in the track equipment and in the vehicle equipment, which devices will now be described in detail in connection with the various figures illustrating them.

30 Referring now more particularly to Figures 2 and 3 there is shown one of the track magnets and a constructional form of armature adapted to be influenced magnetically thereby. The magnet 16 or 17 of a block is 35 positioned between certain cross ties 120 of the track or block. The magnet is shown as having an extended pole piece 121 composed of soft iron and attached rigidly to the core thereof. The pole piece is of sufficient length to extend between and across the ties, the end portions of said pole piece resting upon filler blocks 122 and said pole piece being fastened firmly in position by bolts 123 passing through the filler blocks and the ties. 40 On the vehicle there is provided a boxing 124, composed of bronze or other non-magnetic material. Extending horizontally through the boxing is a rock shaft 125 journaled in side walls of said boxing, and mounted loosely on the shaft is a rocker 126, also composed of non-magnetic material. Said rocker carries two segmental parts, one of said parts 127 carrying the armature 16^a composed preferably of soft iron adapted to open or close one of the signal circuits, as heretofore described. The boxing 124, is provided with a shoulder 128 in the path of the rocker member 127, so as to limit or arrest the gravity movement of the rocker in one direction. 45 The other member 129 of the rocker is provided with the switch member 45 composed of bronze or other non-magnetic metal, the same being electrically insulated at 130 from the rocker. The boxing 124 is offset at 131 for the purpose of receiving a bridge plate

132, on which bridge plate is mounted the contacts 133, 134 for the terminals of the conductors 58, 60 in the case of the track magnet 16, or for the conductors 59, 60 in the case of the track magnet 17, said bridge 70 plate 132 being insulated electrically from the offset part of the boxing.

75 It is apparent that the rocker will swing by gravity in one direction for its member 127 to contact with the stop shoulder 128, the contacts 134 being in engagement with the insulation 130 on the rocker; but as the vehicle moves over the track magnet which is energized as heretofore described, then the movement of the armature 16^a through the 80 field afforded by the extended pole piece 121 of the magnet will influence the rocker 126 so as to turn it through an arc of predetermined length, whereby a magnetic impulse will swing the rocker for the switch 45 to 85 engage electrically with the contacts 133, 134, thereby closing the circuits to one of the signal controlling solenoids, the arcuate movement of the rocker affording a wiping contact.

90 In the constructional form of the circuit maker illustrated in Figures 4 and 5 the magnet 47 to be carried by the moving vehicle past the interference 30 is shown as consisting of a plurality of coils and cores, the latter being connected at one end by a bridge plate 135 composed of soft iron and operating to complete a magnetic circuit. Said magnet 47 is attached in a suitable way to a plate or other member 136 of a boxing 137, 95 the latter being composed of bronze or other non-magnetic material. The cores of the magnet are shown in Figure 4 as extending below a part of the boxing 137 but the lower end of the boxing is offset downwardly at 100 138 in order to provide a chamber adapted to encase the armature 47^a of said circuit maker. This armature is carried by two bent arms 139 constituting a rocker, supported by a horizontal rock shaft 140 journaled within 105 the boxing 137. The arms 139 of the rocker are extended into the offset 138 of the boxing so that the armature 47^a is adapted to be fastened to the rocker arms in a position to lie within the magnetic field of the magnet 47. 110 The rocker arms 139 are joined at their other ends by a plate 141 to which is attached a bronze or other non-magnetic metal bridge plate 142, the latter being electrically insulated from the rocker. Secured within the 115 boxing 137 is a plate 143 insulated electrically from the boxing, and on this plate 143 is mounted a number of contacts forming the terminals of the conductors 48^b, 106, 115, 54, and 55.

120 The magnetic interference 30 in the constructional form of the circuit maker may be associated with any desired rail, either a or a', of the block. The interference 30 is positioned in contact with a spacer 144 which is 125

in contact with a rail, a' and in contact with this rail is another spacer 145, the whole being bolted solidly together by the bolts 146, whereby the interference 30 is electrically in contact with the spacers 144, 145, the rail a' , and a soft iron or steel binder 147, so that as the circuit maker passes adjacent to the interference there will be formed a closed magnetic circuit through the magnet 47, its poles, the bridge plate 135, the magnetic interference 30, the spacers 144, 145, the rail a' and the binder 147. It will be observed that the interference 30 and the boxing 137 are so related that said interference passes between the poles of the magnet 47 and the armature 47^a, whereby the interference 30 diverts the magnetic field for the armature 47^a with the rocker 139 to be free to swing to the full line position of Figure 4, thus interrupting the several circuits because the bridge plate 142 moves away from the series of contacts for the specified conductors.

As in the construction of the armature for the track magnet, the armature for the circuit maker is operated to secure a wiping contact between the plate 142 and the contacts within the boxing for the specified conductors of the circuit.

In the constructional form of the speed governor 65 illustrated in Figures 6 and 7 the various parts are housed and cased within a boxing 148 which may have the particular form shown or any other form appropriate for the purpose. Said boxing is provided at one side with an extension 149, the opposite walls of which are provided with openings 150 so that a car axle 151 extends loosely through these openings. If desired, suitable means may be provided for closing the space between the boundary edges of the openings and the axle to exclude dirt and retain the lubricant within the casing. The axle 151 carries a master gear 152 fast with the said axle, said master gear being adapted to mesh with a pinion 153, the latter being mounted on a combined shaft and solenoid core 154, and said gear pinion 153 being made fast with the element 154 by a key 155, whereby the gear is connected with the element 154 so as to rotate at all times therewith and at the same time said gear 153 can partake of the desired sliding movement in order to position said gear out of mesh with the master gear 152. The element 154 is composed of magnetizable metal so as to serve as a core of a solenoid 175 and said element 154 acts as the shaft for the gear pinion 153, to which end the element 154 is supported by a ball bearing 156 provided in a plate constituting a part of the boxing 148. The element 154 is integral with or attached solidly to a tubular spider 157, the parts of which extend radially to the element 154 and rotate therewith. Within the tubular spider are the centrifugal weights 158, 159, each provided with a guide sheave

160. A flexible band 161 is anchored in a suitable way to a part of the rotary spider 157, said band extending from its anchored point around the sheaves 160 of the weights 159, 158 respectively, thence around a direction sheave 162 mounted in the spider between the weights, and thence the flexible band extends and is attached to a bolt or pin 163. The tubular spider is provided with a tubular shaft 164, extending loosely through the member 165 of the boxing 148, the extremity of said tubular shaft being journaled by a ball bearing 166 within said member 165, whereby the rotary spider 157 is supported at one end by the element 154 rotating in the bearing 166, whereas on the other side the spider is supported by the tubular shaft 164, working within the bearing 166, as a result of which construction the spider is adapted to rotate with great freedom and ease within the boxing 148. The tubular shaft 164 is provided with a longitudinal slot 167 through which extends the cross pin 163 so that the pin rotates freely with the tubular shaft and is adapted to slide within the slot 167 thereof. Said 90 slidable pin 163 is retained normally in a retracted condition by a retractor shown as a spring 168 encased within the tubular shaft 164. One end of said spring being attached to the slidable pin and the other end being anchored by a cross pin 169 fixed to the tubular shaft, the spring being contracted when the weights 158, 159 are in contact with stop shoulders 170 of the tubular spider 157.

A metallic sleeve 171 is fitted loosely on the tubular shaft 164 so as to slide freely upon said tubular shaft and rotate therewith, one end of said sleeve being attached fixedly in a suitable way to the cross pin 163. Said slidable sleeve is provided exteriorly thereof with a sleeve 172 composed of insulating material, and this insulated sleeve carries the switch member 66 of the speed control mechanism, said switch member being represented in Figure 6 as a metallic sleeve composed of current carrying metal. The switch sleeve 66 is in the path of a series of contacts which constitute a group of governor contacts 67, 68, 69, 70, 71 heretofore described. Contacts 67, 68 and 70 are attached to a bed of insulating material 173 fastened to a wall of the extension 165 forming a part of the casing 148, whereas the bed 174 is also attached to the casing. The insulating beds 173 and 174 are positioned at opposite sides of the tubular shaft and the switch sleeve, but in the normal position of the parts shown in Figure 6 the switch sleeve is in such relation to the contacts that no current is flowing through the governor mechanism of the speed control.

The shiftable gear 153 is adapted to be thrown into mesh with the master gear 152 by the action of the sliding solenoid 175 cooperating with the element 154, the latter con-

stituting the core of said solenoid 175. As shown, the gear 153 is attached rigidly to a hub 176 extended or prolonged to form a sleeve 177, the latter being slidably fitted on the element 154 and being connected therewith by the spline 155, as heretofore described. The sleeve 177 carries an insulation 178, upon which is wound the coil of the solenoid 175, and around this coil is a casing 179 of insulating material. Said casing is provided with two metal contact rings 180, 181 positioned exteriorly on the casing and attached firmly thereto, said contact rings being electrically and mechanically supported by the insulating casing 179, said rings being electrically connected to respective ends of the coil of the solenoid 175. Current from any suitable source of energy is supplied to the solenoid coil 175 for energizing the same. As shown, contacts 182, 183, 184 are supported by a member 185 in a fixed position within boxing 148; the contact 182 is positioned for electrical engagement at all times with the contact ring 181; the contact 184 is positioned for electrical engagement at all times with the ring 180; and these two contacts are in a circuit with battery 36 and a suitable switch 187, said switch being operable to close the circuit for battery 36 to energize the coil of the solenoid 175. The contact 183 is in electrical connection with one contact 67 of the group of governor contacts, so that when the solenoid 175 is energized and said solenoid and the gear 153 are shifted by the action of the element 154 in order to bring the gear 153 in mesh with master gear 152, then the contacts 182, 183 are in electrical engagement with the ring 181 for current to be supplied to the governor contact 67 from battery 36. It is apparent that the solenoid 175 may be cut out by manipulation of the switch 187, or said switch may close the circuit for current from battery 36 to energize coil 175, whereupon said coil cooperates with the element 154 to impart sliding movement to the solenoid and position the gear 153 in mesh with the master gear 152, thus bringing the speed governor into condition for operation, but should the circuit be opened, then the solenoid is moved by the action of a spring 188 to a position for disengaging gear 153 from master gear 152.

In Figures 8, 9, 10 and 11 there is illustrated a constructional form of signal controlling solenoid having a retardation device associated therewith in accordance with this invention for actuating a switch with an appreciable interval of time intervening the descent of the solenoid plunger and the interruption of a circuit by said switch, the solenoid, shown and about to be described, being suitable for either solenoid 39 or 40 hereinafter referred to in connection with the system of Figure 1. I have elected to illustrate 65 the construction of Figures 8, 9, 10 and 11 as

being appropriate to the solenoid 40, but it will be understood that the illustration and description are applicable as well to the solenoid 39.

A supporting spool 190 is provided for the coil of solenoid 40. To the bottom end of this spool are rigidly attached hangers 191 insulated electrically from said spool at 192. The core 40 of the solenoid is provided at its lower extremity with a pin or bolt 193 which carries a block 194 of insulating material, through which block extend the switch members 43, 44, heretofore described. Said switch members are electrically insulated from each other by the block 194, said block and the switch members being movable with the solenoid plunger 40^a. The switch members 43, 44 are positioned in the insulating material composing the block in substantially the same horizontal plane, so that the switch member 43 is adapted to have electrical engagement with contacts 195, 196 of the conductors 48 and 49, respectively, whereas the other switch member 44 is adapted for electrical engagement with the contacts 197 and 198 to which are connected the conductors 55, 57, respectively, whereby the circuits are closed when the solenoid coil 40 is energized to lift the plunger. The other switch member 201 is positioned in the block 194 above the switch members 43 and 44 so that the additional switch member 201 will have electrical engagement with the contacts 199, 200 to which are attached the conductors 52, 53, whereby the circuit is closed by the switch 201 coming into engagement with the contacts 199, 200 upon the descent of the plunger 40^a due to de-energization of solenoid coil 40. It is thus apparent that in the raised position of the solenoid plunger 40^a the switches 43 and 44 make the contacts so as to close the circuit formed in part by the conductors 48, 49 and 55, 57, respectively, but in the down position of the solenoid plunger the switch 201 closes the circuit through the conductors 52, 53 for the purpose hereinbefore mentioned.

At the upper end of solenoid 40 the internal sleeve of the spool 190 is extended to form a piston chamber 202, and above this piston chamber is a piston cylinder 203, the diameter of which cylinder exceeds that of the piston chamber 202. A double piston operates within the piston chambers, the large piston head 204 sliding within the cylinder 203, whereas the smaller piston head 205 slides within the chamber 202. The two piston heads are connected by a rod 206 all of which is composed of non-magnetic material. Said rod is hollow for a part of its length, as at 207, and in the rod is a by-pass 208, the latter being controlled in part by a check valve 209. The by-pass 208 terminates in two ports, one above the piston head 205 and the other below said piston head so that the

by-pass is adapted, when the valve is lifted, to establish communication between piston chambers 202, 203, the speed of descent of the piston rod 206 and the piston heads 204, 5 205 depending upon the escape of air through a restricted controlling passage 210 provided in the small piston head 205.

Attached rigidly to the upper end of the piston cylinder 203 are brackets 211 electrically insulated from said cylinder. Said 10 brackets carry contacts for the switches 91, 92, the contacts for the switch 91 being adapted for electrical connection with the conductors 98, 99, whereas the contacts for the switch 92 are adapted for electrical engagement with conductors 101, 105, all as clearly indicated in Figures 8, 9 and 11. The switches 91, 92 are carried by a sliding block 212 composed of insulating material positioned for movement between the brackets 211. The switch-carrying block 212 is adapted to be sustained in a raised position by a spring housing 213, the lower end of which is in contact with the piston head 204. Within 15 this housing is a coiled spring 214, the lower end of which is seated upon the corresponding end of spring housing 213, but the upper end of the spring bears against a yoke 215 attached to the cylinder 203.

With the coil of solenoid 40 energized, the plunger 40^a is raised to sustain the piston rod 206 and the pistons 204, 205 in raised positions, thus lifting the switch block 212 and the switches 91, 92 to the raised position as shown more particularly in Figure 9 so as to close the circuits from the conductors 99, 98, and 101, 105. Upon solenoid 40 becoming de- 30 energized, plunger 40^a drops, as heretofore described, so as to free said plunger from contact with the piston rod 206, but the compression of air in chambers 202, 203 due to the movement of the piston heads 204, 205 checks the sudden drop of the piston rod because the air compressed in cylinder 203 by 35 the piston 204 can escape slowly through the restricted passage 210 of piston head 205, piston chamber 202 being open to the atmosphere through ports 216. The slow downward movement of the piston head 204 continues until piston head 205 passes ports 216 when chamber 203 is vented to allow a quick drop of switch block 212 after retarding the descent of said switch block 212 as compared with the drop of the plunger 40^a so that an appreciable interval of time elapses between the drop of the plunger 40^a and the dropping of the switch block 212, and thus the switches 91, 92 open their respective circuits shortly after the plunger 40^a shall have been lowered. 50 Upon the upward movement of the plunger 40^a when the coil is again energized, the bypass 208 is opened by lifting the valve 209, thus venting the piston cylinder 203 to allow the required upward movement of the double piston, and during the upstroke of said 55

piston the switch block 212 and the switches 91, 92 are raised to their normal positions, the spring 214 being compressed.

I will now proceed to describe the automatic means for effecting the application of the brakes, said automatic brake-applying means being under the control of the solenoid 73 to which reference has heretofore been made. Said Figure 12 illustrates diagrammatically the fluid pressure brake ordinarily employed on moving vehicles, wherein 70 217 refers to the brake cylinder, 218 the main train line, 219 the main reservoir connected with the train line through the engineer's valve 220, 221 the triple valve connected with the train line and with the brake cylinder, and 222 the auxiliary reservoir connected with the triple valve. It will be understood by those skilled in the art that the train line 218 is charged from the main reservoir 80 219, that the pressure in the train line is equal to or exceeds the pressure in the auxiliary reservoir, and that there is no pressure in the brake cylinder 217, the brakes being released. When the train line pressure is reduced by a manual operation of the engineer's valve 220, then a difference in pressure is established between that of the train line 218 and the auxiliary reservoir 222, which difference in pressure operates the triple 85 valve to admit the fluid pressure from the auxiliary reservoir into the brake cylinder for applying the brakes. It will be understood, further, that in releasing the brakes the operations involve an increase in the train line pressure supplied by the engineer's valve 90 from the main reservoir 219 so as to operate the triple valve for the purpose of venting the brake cylinder to atmosphere and connecting the train line with the auxiliary reservoir 100 so as to bring the pressure in said auxiliary reservoir to normal, the triple valve remaining normally in a condition to vent the brake cylinder to atmosphere, and the auxiliary reservoir being supplied with fluid under 105 pressure from the train line.

The automatic mechanism which I employ in my system of train control is so related to the brake mechanism that said brake mechanism may be and is applied independently 115 of any action on the part of the engineer, whereby I am enabled to effect a reduction in the speed by the application of the brake in accordance with the conditions of the speed governor or to bring the train to a full stop, also controlled by the speed governor. In this connection it is desired to state that the automatic brake control mechanism used in my system does not in any way interfere with the application of the brakes by manual operation of the engineer's valve, but under certain conditions the application of the brake by the automatic mechanism may supplement the application of the brakes under 120 125 130

the manual control by the operation of the engineer's valve.

I employ a valve cylinder 223 constructed to produce two chambers 224, 225 at all times in communication with each other, and the cross sectional area of one chamber (225) being substantially less than the corresponding area of the other chamber (224). The valve cylinder 223 is connected by pipes 226, 227 with the brake cylinder 217 and the triple valve 221, respectively, so that the brake cylinder is normally vented through the pipe 226, the chamber 225 of the valve cylinder, the pipe 227 and triple valve 221. Communication between the chamber 225 of the valve cylinder and the pipe 226 is obtained by ports 228 for a purpose presently described.

Positioned within the valve cylinder 223 is a differential piston valve consisting of a piston head 229, a connecting member 230 and another piston head 231, the piston heads 229 and 231 being of different diameters so that the larger piston head 229 operates in the chamber 224, the smaller piston head 231 operating within chamber 225. In the normal position of the piston, the larger piston head 229 is in contact with a stop 232 provided on one head of the valve cylinder so that in said normal position the piston head 229 uncovers a port 233 through which communication from the lower part of chamber 224 is established with a by-pass chamber 234. The valve cylinder 223 is provided with an additional chamber 235 separated from the by-pass chamber 234 by an intervening wall 236 in which is provided a by-pass port 237, the latter port being normally closed by a valve 238 provided on a rod 239 resting upon or forming a part of the plunger 240 of the solenoid 73, it being understood that the valve rod 239 is composed of bronze or other non-magnetic material. Said valve rod 239 operates in a bushing 240' provided in one wall of the by-pass chamber 234, said bushing having a valve seat 241 adapted to be occupied by the valve 238 when the plunger 240 drops and coil 73 is de-energized, whereby the valve 238 closes a vent through the bushing from the by-pass chamber. The additional chamber 235 is in direct communication with the main reservoir 219 by a pipe 242, said chamber 235 being normally in communication with the chamber 224 by a port 243, which port is not covered at any time by the movement of the piston head 231 within the chamber 225. In the normal position of the brake mechanism, as shown in Figure 12, solenoid 73 is energized and plunger 240 is raised for the valve 238 to close the communication between chamber 235 and by-pass 234, whereas the brake cylinder is vented to atmosphere through the triple valve in the manner heretofore described, and the space below the piston valve head 229 is vented to atmosphere through port

233, by-pass 234 and the valve rod opening in bushing 240. In the described position pressure from the main reservoir is established in the chamber 224 so as to act upon the heads 229, 231 of the piston valve, but owing to the greater area of the piston head 229, the valve is in the position shown in Figure 12, the head 229 being in contact with the stop 232, and communication between the ports 243 and 228 is cut off by the smaller piston head 231. When the coil of solenoid 73 is de-energized, plunger 240 drops, permitting the rod 239 and the valve 238 to be forced downward by the pressure in chamber 235. The descent of the rod and the valve opens communication between the chamber 235 and the by-pass 234, said valve occupying the seat 241 so as to close the vent to atmosphere of by-pass 234. The motive fluid supplied to chamber 235 is thus free to flow through port 237, chamber 234 and port 233, to the space below the piston head 229, the effect of which is to impart upward movement to the differential valve owing to the equalization of pressure against the respective surfaces of piston head 229 and the pressure of the fluid against the smaller piston head 231, whereby the differential piston valve is automatically lifted when the pressure from the chamber 235 is supplied to the space below said piston head 229. The operation of lifting the differential valve moves the piston head beyond the port 228 so that the motive fluid from the main reservoir 219 flows through the pipe 242, chamber 235, port 243, chamber 225, port 228 and pipe 226 direct to the brake cylinder, whereby the brakes are applied automatically by pressure supplied directly from the main reservoir 219. In this condition of the parts it is not possible for the engineer to apply or release the brake by the operation of the engineer's valve 220, for the reason that the piston head 231 of the differential piston valve is between the port 228 leading to the brake cylinder and the pipe 227 leading to the triple valve, nor can the engineer manually operate the valve 220 to release the brakes, so that my automatic mechanism cuts out the manual control of the brake mechanism by the engineer at certain stages in the operation of the system.

Should the speed be reduced within the required limits or the signal indication change, the coil of solenoid 73 is energized and plunger 240 is raised, unseating the valve 238 from seat 241 and closing the communication between the by-pass 234 and chamber 235, which operation of lifting the valve opens the vent through the bushing 240 from the by-pass 234 and port 233 leading to the space below the piston head 229, thus opening the lower part of the valve cylinder to atmosphere and allowing the differential valve to descend owing to the difference in area, whereupon the piston head 231 is interposed

between the ports 228 and 243 so as to cut off communication from the main reservoir to the brake cylinder and re-establish the communication from the brake cylinder to the triple valve through the port 228, chamber 225 and pipe 227, thus venting the brake cylinder through the triple valve and releasing the brakes. It is apparent that at any stage in the operation of the automatic mechanism 5 the engineer may vent the train line through the engineer's valve and so operate the triple valve as to effect a continuous application of the brakes in order to still further reduce the speed or, if desired, to bring the vehicle to a 10 full stop.

When the vehicle is not equipped with a main reservoir 219 or engineer's valve 220, then it is preferred to employ an auxiliary air reservoir 244, shown in dotted lines in 15 Figure 12, said reservoir 244 being interposed between the train line 218 and the pressure chamber 235 of my automatic brake controlling mechanism. Said reservoir 244 is connected directly with pipe 242 and said 20 reservoir is connected with the train line by an additional pipe 245, the same being provided with an automatic check valve 246. It is apparent that each time the train line pressure reaches normal condition, the pressure in the reservoir 244 is brought to the same condition, but when the train line pressure is reduced check valve 246 prevents the air from escaping out of the reservoir 244. It is apparent also that under normal conditions the train line 218 is being charged from 25 the main reservoir through the engineer's brake valve, and that when the brake mechanism is operated to automatically apply the brakes, the pressure required for the operation of such automatic brake mechanism is supplied from the reservoir 244 and, further, that in the event of reduction of pressure in the reservoir 244 the motive fluid is supplied from the train line to said reservoir through 30 the pipe 245, the effect of which is to apply the brakes by pressure of the train line acting through the reservoir 244.

In a preferred form of the invention the valve rod 239 is preferably disconnected 35 from the solenoid plunger 240. In operation the plunger 240 drops rapidly when solenoid 73 is de-energized, but the valve rod 239 descends to a point where its lower end is free from contact with plunger 240 so as 40 to leave an intervening space between the plunger and the valve rod. Now, when the coil is energized, and the plunger 240 is lifted quickly, said plunger acts forcibly or with a blow against the rod 239 so as to raise the 45 rod and the valve by practically a hammer blow.

I will now proceed to describe the constructional form of the solenoid 72 (shown in Figure 13) which operates to energize and 50 de-energize the brake-controlling solenoid

73 and opens and closes the circuit whereby the power is supplied to or cut off from the vehicle driving motor. The coil of the solenoid 72 is wound upon a spool 247 fixedly supported in position in any suitable way. 70 Insulations 248, 249 are attached to the respective end portions of the spool, said insulations 248 carrying spring contacts 250, 251 in circuit with conductors 80, 81, respectively. The plunger 72^a of the solenoid is provided at its upper part with a rod 252 composed of non-magnetic material, such as bronze, and this rod is equipped with a block 253 of insulating material. The switch member 79 is attached to this block so as to be movable with the rod 252 attached to the plunger, said switch member 79 being adapted for electrical engagement with the spring contacts 250, 251 so as to close the circuit to the coil 73. The other insulation 249 supports spring contacts 254, 255 adapted to be engaged electrically by the switch 78, the latter being electrically insulated from the plunger by an insulating block 256 which is secured to the lower part of the plunger by 80 a stem 257. It is apparent that the switch members 78, 79 are attached to the upper and lower end portions respectively of the solenoid plunger 72^a; further, that when the coil 72 is de-energized the plunger drops in 85 order to move the switches 78, 79 from the contacts 254, 255 and 250, 251, respectively, thus interrupting the circuit to the coil 73 and the circuit which supplies energy to the motor 75. A quick movement is imparted 90 to the plunger and the switches by a spring 258, encased within the spool of the solenoid so as to have one end seated against the insulation 248 and the other against a shoulder of the solenoid, said spring being composed 95 of non-magnetic material.

A construction form of the solenoid 10 associated with the rails of a block and adapted to control the energization of the track magnets for two blocks in the rear of the block with which the solenoid is associated is illustrated in Figures 14 and 15 of the drawings. The coil of the solenoid 10 is wound upon a spool 259, and within this solenoid plays the plunger 18. Attached rigidly to the bottom of the spool and insulated electrically therefrom are hangers 260 which support the contacts 261 with which contacts the switches 19, 20 and 21 are adapted to respectively engage, all as clearly 110 shown in Figures 14 and 15. The switches referred to are embedded in a switch block 262 composed of insulating material, the end portions of the switches being exposed for electrical engagement with the contacts 261. 115 The downward movement of the plunger and the switch block is limited by a yoke 263 attached to the lower part of the solenoid spool 219. Attached to the upper end of the spool is a bracket 264 in which is 120

mounted an adjusting screw 265 adapted to regulate the tension of a coiled spring 266, the lower end of which spring is seated in a cup-shaped bearing 267 which works loosely in the spool of the solenoid the downward movement of which cup shaped bearing is limited by shoulders in the solenoid spool as shown and the bottom of which bearing 267 is adapted normally to contact with the upper end of the core 18, in which position the contacts 261 are in electrical engagement with the switch members 19—20—21.

The solenoid described is a three-position solenoid as follows:—With the coil 10 energized under normal conditions of the track the plunger 18 is lifted up to and in contact with the bearing 267, but the magnetic flux is not of sufficient strength to compress the spring 266 so that the switches 19, 20 and 21 make electrical engagement with the several contacts 261; when the coil 10 is de-energized the plunger and the switch block drop by gravity so that the switches are free from the contacts 261, thus interrupting the circuits to the track magnets and when the increased flow of current from the battery through the coil 10 takes place owing to the current being shunted out of the coil 11 by the presence of a vehicle in the block, such increased flow of current increases the magnetic flux of the solenoid coil 10 for the purpose of raising the plunger 18 above the normal position, the effect of which is to lift the switch block and the series of switches so as to again interrupt the circuits, such upward movement of the solenoid plunger beyond the normal position tending to compress the spring 266, but when the flow of current through the solenoid 10 is restored to normal the spring reacts in order to depress the plunger and the switch block for the switches to again make electrical connection with the contacts 261. Briefly stated, the solenoid 10 controls the switches so that they partake of three positions, in one of which the switches close the circuits to the track magnets, and in the up position and down position the switches interrupt the circuits. It will be noted that with solenoids 10, 11 and battery 14 in series through the track rails, the current will be of sufficient strength only to lift core of 10 to normal position.

A constructional form of the solenoid 11 connected across the rails of a block is shown in Figures 16 and 17, wherein the coil of the solenoid is wound upon a spool 278, within which spool operates the plunger 11^a. The lower end of the plunger carries an insulating block 279 in which is embedded the switch member 11^b, the latter being adapted to have electrical engagement with the contacts composing the group 24, as shown in Figure 17. Said contacts 24 are supported by hangers 280 secured to the lower head of

the solenoid spool 278 and insulated electrically therefrom. The energy of the solenoid lifts the plunger and the switch for the contacts 24 to be in engagement with the insulated block 279 substantially as shown in Figures 16 and 17, but when the coil is de-energized the plunger and the switch block drop by gravity so that the switch member 11^b has electrical contact with the switch contacts 24 for the purposes hereinbefore explained.

A constructional form of the cut-out solenoid 31 is shown in Figures 18 and 19 for the purpose of interrupting the circuits in case the energy of the battery 14 drops below a predetermined standard. The coil 31 has its respective ends connected with the respective poles of battery 14, and it is wound upon a spool 281 within which operates a plunger 282. To the upper end of this plunger is attached a stem 283 composed of non-magnetic material, so that the stem is movable with the plunger, but upward movement of the plunger and the stem are opposed by a spring 284. Secured rigidly to the upper part of the solenoid spool 281 is a bracket plate 285 having an upstanding post 286 on which is mounted a bellcrank lever 287 by a pin 288, one arm of this bellcrank lever being weighted at 289, whereas the other arm of the lever engages a shoulder 290 of the stem 283. The bellcrank carries a bridge plate 291^a electrically insulated from the lever, said plate being adapted to bridge the space between adjacent contacts 291, 292 which are mounted on the head of the solenoid spool and electrically insulated therefrom. The contacts 291, 292 are attached to conductors leading from the battery 14, to the track circuits and track magnets and the coil 31 is wound to a predetermined resistance so that when the strength of the current drops below the predetermined standard, the coil will not hold up the plunger 282, thus allowing the latter to descend in order to withdraw shoulder 290 from the path of the bellcrank 287, at which time the weight 289 snaps the plate 291^a free from the contacts 291, 292, thus interrupting the battery circuit so as to result in de-energizing the track magnets for the purpose of giving a danger signal on the moving vehicle, all as heretofore described.

In Figure 20 of the drawings there is illustrated diagrammatically a system for each car of an electrically propelled train, means being provided whereby the necessary electrical connections are automatically made when the cars are coupled in the ordinary way. As shown, a positive conductor 293 is attached to contacts 294 and 295 positioned at the respective ends of the car.

Another conductor 296 extends the full length of the car to serve as a common negative connection, and at the opposite ends of

the car this conductor 296 is attached to contacts 297, 298, respectively.

The battery 36 of the system heretofore described is connected across the positive and negative conductor 293 and 296, respectively.

Another conductor 299 extends the full length of the car, the opposite ends of said conductor being in electrical engagement with contacts 300, 301, respectively, and from this conductor 299 extends a branch conductor 80 which extends to the switch member 79 of solenoid 72 and has a branch connection with the solenoid 73 adapted, as heretofore described, to set into action the automatic 10 brake mechanism of Figure 12, said solenoid 73 being connected by the conductor 82 with the common negative lead 296. It will be understood that the lead 299 constitutes a common positive connection throughout the train 15 for the solenoids 73 which control the automatic brake devices. In like manner there is a common positive lead 302 extending throughout the train for controlling the signals, the opposite ends of said conductor 302 being attached to contacts 303, 304 positioned 20 at the opposite ends of the car. From this common positive lead 302 extends two conductors 305, 306 leading respectively to duplicate signal mechanisms provided on each motor 25 car. Each of the two signal equipments include the signals 33, 34, 35 and the resistance 38, as heretofore described, and in addition thereto each signal equipment includes a magnet 307 adapted to control the armature 308, and the latter in turn actuates a switch 309. Associated with each of the two aforesaid signal equipments on the motor car is a 30 manually operated switch 310 which is attached to or operated in unison with the ordinary controller switch, so that each time the controller switch is operated by the motorman the switch 310 will be simultaneously operated therewith to cut the signal equipment into and out of the circuit.

The circuit connections are as follows:— The magnet 307 is connected, as heretofore described, by the conductor 305 with the positive signal conductor 302, and from said magnet 307 a conductor 311 leads to the switch 310, said conductor 311 being branched as shown so that the switch in either of its extreme positions will be in electrical engagement with said conductor and from the switch 310 the conductor 312 leads to the negative lead 296, said conductor 312 being branched as shown so as to afford a contact for the switch 310 in either of the extreme positions thereof, said switch 310 being adapted to assume a neutral position intermediate the contacts of the conductors 311, 312, as shown at the left of Figure 20. The armature 308 has a direct connection with the positive lead 293 by a conductor 313, and this armature is adapted to open and close the circuits to the

different signals 33, 34, 35 by actuating the switch 309.

When the clear signal 33 is displayed under the normal conditions of operation, solenoids 39 and 40 are both energized, as heretofore described, and the full current from the battery 36 flows through the magnet 307 attracting armature 308 which moves switch 309 into electrical connection with the conductor 50 leading to the clear signal 33, the negative 70 connection with the battery being through the resistance 38, conductor 311, controller 310 and conductor 312 to the common negative lead 296. When the magnet 39 is de-energized under conditions heretofore described, 75 the path of the current is through resistance 314, reducing by substantially one-half the flow of current through the magnet 307, permitting the armature 308 to move to a position where the switch 309 is in contact with 80 a conductor 51 leading to the caution signal 34, cutting out the clear signal and cutting in the caution signal, the negative connections back to the battery for same being through the path of the current is through resistance 85 90 With both solenoids 39 and 40 de-energized there will be no current flowing from the battery through the magnet 307, and accordingly the armature 308 will move into position for said armature to be out of contact with 95 switch 309 and to make contact with conductor 53 leading to the danger signal 35.

Assuming that the equipment of Figure 20 is applied to a motor car at the front end of the train adapted to travel in the direction indicated by the arrow at the right of said Figure, the controller switch 310 at the right of my equipment occupies the position shown for the purpose of cutting into service a solenoid 316 which in turn cuts into service 100 the solenoids 39, 40, 72, 84, 85 so as to operate the signal equipment at the corresponding end (right hand) of said motor car, but with the motor car equipped, as in Figure 20, at the opposite end of a train and adapted to travel in an opposite direction, then the right controller switch 310 is shifted into a neutral position, and the left controller switch 310 is shifted into an opposite position toward the left so as to introduce into service 105 an independent solenoid 317 at the opposite end of the motor car, which solenoid 317 is adapted in like manner to introduce into service all the solenoids 39, 40, 72, 84 and 85, 110 175, for the purpose of influencing the display of signals provided at the left of Figure 20, it being understood that when solenoid 317 is in service then the companion solenoid 316 is automatically cut out of service.

Associated with the right solenoid 316 of Figure 20 is a lead 318 extending the full length of the train and having contacts 319, 320 at the respective ends thereof, and from this lead 318 extends a conductor 321 having 115 120 125 130

two branches, one of which extends to a member 310^a of the switch 310, whereas the other branch leads direct to the coil of solenoid 316, from which coil leads a conductor 322 extending to a contact point 323 which is in co-operative relation to a spring contact 324 adapted to make electrical connection with the spring contact 297 of negative conductor 296, thereby energizing the coil of solenoid 316.

In like manner, the solenoid 317 at the left of Figure 20 is associated with a lead 325 extending the full length of the car and connected at its respective ends with the spring contacts 326, 327, and from this lead 325 extends a conductor 328 having branches, one of which extends to the left controller switch 310^a, and the other of which extends to the coil of solenoid 317, from which solenoid extends a conductor 329 extending to a contact 330 adapted to make electrical connection with the spring contact 331 adapted, when the plug is withdrawn, to make electrical connection with contact 297 and thence to the negative lead 293 to the battery 36, whereby when the right switch 310 310^a is in a neutral position and the corresponding left switch 310 310^a is in an operative position the solenoid 316 is cut out of service and the solenoid 317 is brought into service for the performance of the functions heretofore stated.

Another lead 332 runs substantially the length of the motor car, and from the right hand end therefrom extends a conductor 333 extending to a contact in the path of a switch member 334 on the armature of the solenoid 316, so that when the said switch member 334 is dropped it makes contact with a conductor 335 having two branches, one of which leads to contact 336 and the other to contact 337, the latter being adapted to be electrically connected with contact 295 having a direct connection with the positive lead 293.

At the left end conductor 332 leads at 338 to a contact in the path of the switch 339 associated with the armature of the left solenoid 317, and when this switch member is dropped it makes contact with conductor 340 having two branches, one of which leads to contact 341 and the other to contact 342, the contacts 341, 342 being a duplicate of contacts 336, 337 associated with the other solenoid 316.

Assuming that the vehicle has reached its destination when travelling in the direction of the arrow of Figure 20, the motorman before leaving his station pulls the controller switch 310—310^a to a neutral position, but owing to the conductor lead 332 and the connections described, the right solenoid 316 is not cut out of circuit with the battery 36, so that battery current continues to flow through the signal and brake solenoids in order to prevent cutting out the signals, or to applying the brakes during the interval required for the

motorman to walk from one end of the train to the opposite end of the train, but when he reaches the other end of the train, the motorman pulls the switch corresponding to the left switch 310—310^a so as to move said left switch into a position for cutting into service the solenoid 317, whereupon this latter solenoid on the now leading car of the train is adapted to control the solenoids 39, 40, 72, 84, and 85, so that the signals and the automatic brake mechanism will now be influenced by solenoid 317 on the leading car of the train and solenoid 316 will be de-energized simultaneously with the energizing of solenoid 317, thus the solenoids 39, 40, 72, 84, 85—175 on the car that was formerly the leading car but which is now the rear car, will be cut out of service.

Having thus fully described the invention, what I claim as new, and desire to secure by Letters Patent is:—

1. A system of train control embodying electrical means upon a track and a moving vehicle cooperating independently of mechanical contact to effect a reduction in the speed of a vehicle approaching a preceding vehicle, said electrical means operating to effect a speed reduction of the first vehicle proportionately to the distance separating the two said vehicles.

2. A system of train control embodying a track equipment and a vehicle equipment, said equipments being free from mechanical contact one with the other and said equipments mutually cooperating to effect a reduction of the speed of a vehicle approaching a preceding vehicle proportionately to the distance separating the two said vehicles.

3. A system of train control embodying means free from mechanical contact with a track equipment and operating electrically to effect the reduction in speed of one vehicle following a preceding vehicle proportionately to the distance separating the two said vehicles, and means for automatically stopping the movement of the following vehicle as it approaches within a predetermined distance of the preceding vehicle.

4. A system of train control embodying a track equipment and a vehicle equipment, free from mechanical contact one with the other, said vehicle equipment including a cab signal mechanism and a brake mechanism controllable by said signal mechanism, said track equipment and the vehicle equipment mutually cooperating to effect a change in the signal indication and a reduction in the speed of the following vehicle with respect to a preceding vehicle according to the distance separating the two said vehicles.

5. A system of train control embodying an electrically operated track equipment and an electrically-operated vehicle equipment, the latter including a cab signal mechanism and a brake mechanism independent of man-

ual control, said track equipment and the vehicle equipment being free from mechanical contact one with the other and mutually cooperating to effect on a following vehicle 5 a change in the signal indication and a reduction in the speed thereof according to the distance separating said following vehicle from a preceding vehicle.

6. A system of train control embodying a 10 track equipment and a vehicle equipment, the latter including a cab signal mechanism and a fluid pressure brake mechanism independent of manual control, said track equipment and the vehicle equipment being free 15 from mechanical contact one with the other and mutually cooperating to effect a change in the signal indication on the following vehicle according to the distance separating said following vehicle from a preceding vehicle 20 and to effect a reduction in the speed of the following vehicle proportionately to the distance separating said following vehicle from a preceding vehicle, said brake mechanism on the following vehicle being 25 controllable by the signal mechanism thereon.

7. A system of train control embodying a 30 track equipment and a vehicle equipment, the latter including a cab signal mechanism and a fluid pressure brake mechanism independent of manual control, said track equipment and the vehicle equipment being free 35 from mechanical contact one with the other and mutually cooperating to effect a change in the signal indication on the following vehicle according to the distance separating said following vehicle from a preceding vehicle and to effect a reduction in the speed of the following vehicle proportionately to the distance separating said following vehicle 40 from a preceding vehicle, said brake mechanism on the following vehicle being controllable by the signal mechanism thereon, said track equipment and the vehicle equipment including, also, mutually cooperating 45 devices whereby the brake mechanism is brought into service for stopping the following vehicle when the latter approaches a preceding vehicle within a predetermined distance.

50 8. A system of train control embodying a track equipment and a vehicle equipment, the latter including a cab signal mechanism for indicating clear, caution and danger and a 55 brake mechanism independent of manual control, said track equipment and the vehicle equipment being free from mechanical contact one with the other and mutually 60 cooperating for effecting on a following vehicle a change in the signal indication from clear to caution and from caution to danger according to the distance separating said following vehicle from a preceding vehicle and said 65 brake mechanism being responsive to changes in the signal indications for effecting a reduction in speed of the following vehicle

proportionately to the distance separating the following vehicle from a preceding vehicle.

9. A system of train control embodying an electrical track equipment and an electrical vehicle equipment free from mechanical contact one with the other, said vehicle equipment including a brake mechanism free from 70 manual control and including also a speed governor operating through the medium of the brake mechanism to effect a reduction in the speed of a following vehicle as it approaches within a prescribed distance to a preceding vehicle, said speed governor and the brake mechanism being effective in still 75 further reducing the speed of the following vehicle as it approaches more closely to the preceding vehicle, and the aforesaid devices operating to bring the following vehicle to a full stop when it is within a danger zone 80 in respect to the preceding vehicle.

10. In a system of train control, a track equipment embodying rails divided into blocks, each block having associated therewith a source of electrical energy, a solenoid 90 connected across the rails, a plurality of track magnets and a second solenoid connected across the rails in series with the source of energy and controlling track magnets of blocks positioned rearwardly and influenced 95 by the first solenoid so as to de-energize the track magnets of rearwardly located blocks, in combination with a vehicle equipment including signal mechanism and a brake mechanism separate from manual control, said vehicle 100 equipment including means to traverse the fields of said track magnets and to actuate the signal mechanism or the brake mechanism or both according to the distance separating a following vehicle from a preceding 105 vehicle.

11. In a system of train control, a track equipment embodying rails divided into blocks, each block having associated therewith a source of electrical energy, a solenoid 110 connected across the rails and in series with the energy source, and adapted to be de-energized by the presence of a vehicle in the block whereby current is shunted from the solenoid by the wheels and axles of said vehicle, a plurality of track magnets, and a second solenoid connected with the block equipment so as to be influenced by an increased flow of current when the first solenoid 115 is de-energized, said second solenoid being connected with track magnets of blocks located rearwardly thereof and operating to de-energize the same when the first solenoid is shunted out of service by a vehicle in the block, combined with a vehicle equipment 120 including electrically controlled signal mechanism and electrically controlled fluid brake mechanism, said vehicle equipment traversing the blocks so as to be influenced independently of mechanical contact and by the mag- 125

netic fields of said track magnets for effecting a change in the signal indications and controlling the speed of a following vehicle according to the distance separating the latter from a preceding vehicle.

- 5 12. In a system of train control, a track equipment including rails divided into blocks, a source of electrical energy, a plurality of track magnets, a plurality of solenoids one of which cooperates with the rails and the other of which is connected with track rails in series with the energy source so as to de-energize the track magnets of other blocks when the first solenoid is shunted out of service by the presence of a vehicle in the block, and a magnetic interference in each block, combined with a vehicle equipment including electrically operated signal mechanism and an electrically controlled brake mechanism adapted to be separately or collectively operated by the condition of the track magnets in the respective blocks.
- 10 13. In a system of train control, a track equipment including rails divided into blocks, a source of electrical energy, a plurality of track magnets, a plurality of solenoids one of which cooperates with the rails and the other of which is connected with track rails in series with the energy source so as to de-energize the track magnets of other blocks when the first solenoid is shunted out of service by the presence of a vehicle in the block, and a magnetic interference in each block, combined with a vehicle equipment including electrically operated signal mechanism and an electrically controlled brake mechanism adapted to be separately or collectively operated by the condition of the track magnets in the respective blocks, said magnetic interference on the display of a danger signal operating the brake mechanism to stop one vehicle before the latter emerges from one block to enter a block occupied by another vehicle.
- 15 14. In a system of train control, the combination with a track equipment including a series of track magnets and means for de-energizing the same by the presence of a preceding vehicle within a predetermined distance, of an electrical vehicle equipment including circuit controllers influenced by the fields of said track magnets, and signal mechanism controllable by said circuits for the display of clear, caution and danger signals according to the condition of the track magnets.
- 20 15. In a system of train control, the combination with a track equipment including a series of track magnets and means for de-energizing the same by the presence of a preceding vehicle within a predetermined distance, of an electrical vehicle equipment including circuit controllers influenced by the fields of said track magnets, signal mechanism controllable by said circuit controllers for the display of clear, caution and danger signals according

to the condition of the track magnets, and brake mechanism dependent for its operation upon the display of a caution signal or a danger signal to effect a speed reduction on a following vehicle proportionately to the distance separating the latter from a preceding vehicle.

70 16. In a system of train control, the combination with a track equipment including track magnets and means for de-energizing the same by the presence of a vehicle within a predetermined distance, of an electrical vehicle equipment comprising circuit controllers influenced by the fields of said track magnets, signal mechanism responsive to said circuit controllers for the display of clear, caution and danger signals according to the condition of said track magnets, and a speed reducing mechanism responsive to changes in the signal indication and including brake mechanism and a speed governor cooperating with said brake mechanism.

75 17. In a system of train control, the combination with a track equipment including track magnets and means for de-energizing the same by the presence of a vehicle within a predetermined distance, of an electrical vehicle equipment comprising circuit controllers influenced by the fields of said track magnets, signal mechanism responsive to said circuit controllers, and speed-reducing mechanism responsive to changes in the signal indications for effecting a progressive reduction in the speed of a following vehicle according to the distance separating the latter vehicle from said first named vehicle, said speed reducing mechanism including a brake independent of manual control, a speed governor mechanically actuated by the motion of the following vehicle, and means for co-ordinating the action of said speed governor and the brake mechanism with the changes in the signal indication.

80 18. In a system of train control, the combination with a track equipment including track magnets and means for de-energizing the same by the presence of a vehicle within a predetermined distance, of an electrical vehicle equipment including circuit controlling means adapted to be influenced by passing through the fields of said track magnets, signal mechanism affording a plurality of cab signal indications, and speed-reducing mechanism responsive to changes in the signal indications for effecting a progressive speed reduction of a second vehicle proportionately to the distance separating the latter vehicle from the first named vehicle, said speed reducing means including a governor actuated by the motion of the second vehicle, a brake mechanism independent under certain conditions of manual control, and means for co-ordinating the action of the speed governor and of the brake mechanism with changes in the signal indication.

85 130

19. In a system of train control, a track equipment including a source of energy and a plurality of track magnets in series with said source of energy, each track magnet being provided with an exposed pole piece adapted to be energized by the flow of current from the source of energy through said track magnet, combined with a vehicle equipment, brake mechanism and a signal mechanism, said vehicle equipment including also an encased electromagnetic member positioned to traverse a magnetic field afforded by said track magnet so as to control the signal mechanism and the brake mechanism in a manner to effect a change in the visual signal indication and a reduction in the speed proportionately to the distance separating a following vehicle from a preceding vehicle. 70
20. In a system of train control, a track equipment including a plurality of track magnets connected with a source of energy and including, also, a magnetic interference free from the track magnets and the source of energy, combined with a vehicle equipment embodying a signal mechanism provided with means in a closed circuit for affording indications denoting clear, caution and danger, said signal mechanism embodying a plurality of devices for opening and closing the signal circuit, one of said devices being influenced magnetically by passing through the fields of the track magnets and another of said devices being responsive to the magnetic force of said magnetic interference, whereby the signal mechanism is controllable by the track equipment for displaying signals the character of which is dependent upon a clear track and upon the distance separating a following vehicle from a preceding vehicle. 80
21. In a system of train control, a track equipment including a plurality of track magnets and a magnetic interference in the form of a metallic bar in metallic contact with a rail of a track, combined with a vehicle equipment embodying translating devices to be controlled in electrical circuits on a moving vehicle and a plurality of circuit opening and closing devices provided with poles and armatures, one or more of said circuit opening and closing devices being influenced by the condition of the track magnets and another of said devices being influenced by the presence between the poles and armatures, thereof of the magnetic interference so as to temporarily vary the reluctance of the magnetic circuit. 90
22. In a system of train signal and control, the combination of a track equipment including electromagnets connected with a source of energy, and a vehicle equipment including signal devices and controlling means therefor, adapted to be influenced by said track magnets independent of mechanical contact therewith so as to effect a change in the signal indication according to the distance separating a following vehicle from a preceding vehicle; said vehicle equipment including, also, a brake mechanism, a speed 100
- a following vehicle from a preceding vehicle; said vehicle equipment including, also, a brake mechanism and a speed governor operating upon a change in the signal indication to effect a reduction in the speed of the following vehicle proportionately to the distance separating said following vehicle from the preceding vehicle. 110
23. In a system of train signal and control, the combination of a track equipment including electromagnets connected with a source of energy, and a vehicle equipment including signal devices and controlling means therefor, adapted to be influenced by said track magnets independent of mechanical contact therewith so as to effect a change in the signal indication according to the distance separating a following vehicle from a preceding vehicle; said vehicle equipment including, also, a brake mechanism, and a speed governor 120
- comprising contacts in circuit with the signal-controlling means, a member operated by the movement of the vehicle, a contact-making member the position of which is dependent upon the speed of the vehicle, and operating means for said brake mechanism controllable by the movement of the contact-making member of said speed governor. 130
24. In a system of train signal and control, the combination of a track equipment including electromagnets connected with a source of energy, and a vehicle equipment including signal devices and controlling means therefor, adapted to be influenced by said track magnets independent of mechanical contact therewith so as to effect a change in the signal indication according to the distance separating a following vehicle from a preceding vehicle; said vehicle equipment including, also, a brake mechanism, and a speed governor comprising a series of contacts certain of which are connected with the controlling means for said signals, a member operated by the movement of the vehicle, a second member the position of which is shifted according to the speed of the vehicle, and brake-operating means connected with other contacts of the speed governor and with the signal devices so as to be controlled by the position of the second member of the speed governor so as to effect a reduction in the speed of the following vehicle proportionately to the distance separating said following vehicle from a preceding vehicle. 140
25. In a system of train signal and control, the combination of a track equipment including a series of electromagnets connected with a source of energy, and a vehicle equipment including signal mechanism and signal-operating means responsive to the track magnets 125 for effecting a change in the signal indication dependent upon a clear track or the distance separating a following vehicle from a preceding vehicle; said vehicle equipment including, also, a brake mechanism, a speed 130

governor, a series of electromagnets in circuit with the speed governor and with the signal operating means, and a brake-actuating magnet responsive to the condition of the circuits in which is included the series of magnets so as to control the brake mechanism for effecting a reduction in the speed of the following vehicle proportionately to the distance separating said following vehicle from a preceding vehicle.

26. In a system of train signal and control, the combination of a track equipment including a series of electromagnets connected with a source of energy, and a vehicle equipment including signal mechanism and signal-operating means responsive to the track magnets for effecting a change in the signal indication dependent upon a clear track or the distance separating a following vehicle from a preceding vehicle; said vehicle equipment including, also, a brake mechanism, a brake-controlling solenoid, and a speed governor operatively related to the signal mechanism and to the brake-controlling solenoid for effecting the operation of the brake mechanism to reduce the speed of a following vehicle proportionately to the distance separating said following vehicle from a preceding vehicle.

27. In an inductive train control system, a plurality of trackway devices and vehicle-carried equipment comprising receiving means to form with said trackway devices inductive couples, an air-brake valve, and a speed governor, electrical means cooperating with said receiving means and said speed governor for automatically controlling said air brake valve to obtain upon successive influences of said tracking devices a progressive speed reduction of said vehicle proportionately to the distance separating said vehicle from a second vehicle, and brake-operating means separate from said air brake valve and independent of the automatic control of said speed governor.

28. In a system of train control, the combination with a track equipment, of a vehicle equipment including a plurality of signal devices and a plurality of solenoids the armatures of which are operated with a retarded movement and are influenced by the condition of the track equipment, a brake mechanism, and means responsive to the retarded movement of the signal solenoids for effecting an application of the braking force at an appreciable interval of time subsequently to the de-energization of said signal solenoids.

29. In a system of train control, the combination with a vehicle equipment including a brake mechanism and a signal mechanism, of track magnets, signal-operating solenoids included in the vehicle equipment and influenced by the track magnets, means for retarding the movement of the armatures of said signal-operating solenoids, and means whereby the brake mechanism is responsive to the

retarded movement of said solenoids so as to effect an application of the braking force at an appreciable interval of time subsequent to the de-energization of said solenoids.

30. In a system of train control, the combination with a track magnet, of a vehicle equipment including a relay in a closed circuit with a source of energy and with train operation devices, the armature of which relay is influenced by the magnetic field of said track magnet, a second vehicle relay included in said closed circuit and free from the influence of said track magnet, and a magnetic track interference cooperating with said second vehicle relay for deenergizing the latter and interrupting said closed circuit independently of the influence of said track magnet upon the first relay.

31. In a system of train control, the combination with a track magnet, of a vehicle equipment including a relay in a closed circuit with a source of energy and train operation mechanism, the armature of which relay is movable in the magnetic field of said track magnet, a second vehicle relay in said closed circuit and free from the influence of said track magnet, and a magnetic track interference positioned to pass through an air gap intervening the poles and armature of the second relay to thereby de-energize the latter and interrupt said closed circuit independently of the influence of the track magnet upon the first relay.

32. In a system of train control, the combination with a track equipment including a track magnet and a magnetic interference, of a moving vehicle equipped with electrically operated signalling mechanism, said signalling mechanism being in a circuit, a magnetic circuit breaker in the signal circuit, a rocker forming an element of said magnetic circuit breaker, said rocker being provided with an armature positioned in the field of the poles of the magnetic circuit maker and the magnetic interference of the track being adapted to be interposed between the armature and the poles of the circuit maker, said rocker being encased within a non-magnetic casing equipped with circuit terminals, and a bridge member carried by the rocker so as to have wiping contact with the circuit terminals.

33. In a system of train control, a track equipment including rails divided into blocks each having associated therewith a source of energy, a plurality of track magnets and a plurality of solenoids, one of which is connected across the track, and the other of which is connected across the track in series with the battery, said second solenoid including a coil, a core, a plurality of circuit contacts, and a series of switches carried by the core and insulated electrically therefrom so as to have electrical engagement with the circuit contacts in one position of the core, said switches being connected with track magnets

rearwardly thereof, combined with a vehicle equipment including a signal mechanism and means adapted to be influenced by movement through the fields of said track magnets.

34. In a system of train control, a track equipment including rails divided into blocks and each having a source of energy, a series of track magnets, a solenoid connected across the rails of the block, and a second solenoid connected in series with the track battery across the rails of the block, said second solenoid including a coil, a core, a switch block movable with the core, a series of circuit terminals connected with the track mag-

nets rearwardly thereof, and switch members carried by the switch block and adapted to make electrical connection with the circuit terminals, said second solenoid being influenced by the normal flow of current from the battery to energize the track magnets in the rearwardly located blocks and adapted to be influenced by an increased flow of current when the first solenoid is shunted by the presence of a vehicle in the block so that the second solenoid is operable by such increased flow of current to interrupt the circuits to the track magnets, whereby any break in the circuits operates to deenergize the second solenoid for permitting the core and switches thereof to move to a third position.

35. In a system of train control, the combination with a moving vehicle, a brake mechanism, a speed governor for controlling the operation of the brake mechanism, and a signal mechanism including a solenoid, said solenoid comprising a coil, a core, a switch member independent of the solenoid core, and a retarding device operable by the solenoid core and controlling the switch member so as to open a circuit to the speed governor at a period subsequent to the movement of the core.

36. In a system of train control, the combination with a moving vehicle equipped with a brake mechanism, an electrically operated signal mechanism including a signal-operating solenoid, and a speed governor responsive to said signal-operating solenoid for regulating the operation of the brake mechanism, said solenoid of the signal mechanism including a coil, a core cooperating therewith, a switch member independent of the operation of the core, and a pneumatic retarding device operated by the movement of the core and controlling the movement of the switch member so as to effect a relatively slow movement of the switch member as compared with the movement of the core, whereby the brake mechanism is controlled to apply the brakes at a period subsequent to the change in the signal indication.

37. In a system of train control, the combination with a moving vehicle equipped with a brake mechanism, a speed governor operated by the movement of the vehicle, and

a signal mechanism in circuit with the speed governor, said signal mechanism including a coil, a core, a switch member attached to the core and insulated electrically therefrom, said switch member cooperating with the appropriate circuit contacts, a second switch member independent of the movement of the core, and a pneumatic retarding device operated by the movement of the core in one direction and cooperating with the second switch member for checking the movement of said second switch member so as to effect an application of the brake at a period subsequent to a change in the signal indication.

38. In a system of train control, the combination with a moving vehicle equipped with a brake mechanism, a speed governor operated by the movement of the vehicle, and a signal mechanism in circuit with the speed governor, said signal mechanism including a coil, a core, a pneumatic retarding cylinder, a double piston operating within said cylinder and provided with a valved by-pass, one member of said double piston being provided with a restricted vent aperture, means whereby the double piston is operated by the movement of the core in one direction and is free to move by gravity in the opposite direction subsequent to the descent of the core, and a switch block independent of the core and controllable by the double piston so as to effect an application of the brake mechanism subsequent to a change in the signal indication.

39. In a system of train control, the combination with a moving vehicle equipped with a brake mechanism, a speed governor operated by the movement of the vehicle, and a signal mechanism in circuit with the speed governor, said signal mechanism including a coil, a core, a plurality of switches one of which is directly actuated by the movement of the core, and the other of which is independent of the movement of the core, and a pneumatic retarding device cooperating with the core and the independently movable switch so as to check the movement of said independently movable switch and operate the brake mechanism at a period subsequent to a change in the signal indication.

40. In a system of train control, a track equipment including rails divided to produce a succession of blocks, each block being provided with a source of energy, a series of track magnets, a solenoid having its coil connected across rails of the track and in series with the battery, said solenoid including a series of contacts, a core carrying a switch block, and a switch member attached to the switch block and adapted to engage with the contacts in one position of the core, and a second solenoid connected with the battery and having means whereby it is connected in series with track magnets in the blocks located rearwardly thereof, and a ve-

hicle equipped with an electrical signal mechanism and including means adapted to be influenced by the condition of the track magnets.

41. In a system of train control, a track equipment including rails divided to produce a succession of blocks, each having associated therewith a source of energy, a series of track magnets, a plurality of solenoids, one of which is connected across the rails of the track, and the other of which is connected in series with the battery across the rails of the track and controlling track magnets of blocks positioned rearwardly thereof, and a cut-out solenoid in a shut around the source of energy and including a coil, a core, a movable member operable by the core, and circuit switches adapted to close the circuit of the track magnets in the normal position of the core and to automatically open the circuit upon a decrease from a predetermined standard of the source of energy, combined with a moving vehicle equipped with a signal mechanism and with means controllable electrically by the track magnets.

42. A system of train signal and speed control embodying a track equipment including electro-magnetic elements positioned at intervals and included normally in a closed circuit, a vehicle equipment including relays in a closed circuit, the armatures of which relays are influenced by the magnetic fields of said electro-magnetic elements of the track equipment while free from mechanical contact therewith, train operation signals in said closed circuit, brake mechanism including a vehicle-driven governor, and electro-magnetic devices cooperating with the governor and said signal mechanism for controlling said brake mechanism to effect a reduction of speed correspondingly with the signal displayed for train operation.

43. A system of train signal and control embodying a track equipment including electro-magnetic elements, a vehicle equipment including a plurality of relays the armatures of which are adapted to cooperate with said electro-magnetic elements through lines of force produced at the poles of said electro-magnetic track elements, which lines of force pass through an air gap space intervening the vehicle relays and said track elements, train operation signal means for visually indicating the condition of the track preceding the track section occupied by the vehicle equipment, brake mechanism, and means for controlling the brake mechanism in accordance with the signal indication.

44. A system of train signal and control embodying a brake mechanism and a governor therefor, track devices including means for producing a magnetic field, and a vehicle equipment including a train operation signal, said brake mechanism and vehicle equipment being interconnected electrically for actua-

tion when the vehicle equipment passes through a magnet field produced by the track devices so that the speed of the vehicle may be controlled by the governor in accordance with the train operation signal displayed by 70 said vehicle equipment.

45. In a train control train-carried braking mechanism, a track impulse device controllable by traffic conditions for initiating the action of said braking mechanism, a second track impulse device also controlled by traffic conditions and adapted to set the braking mechanism into action subsequently to the initial action thereof under the influence of the first named track impulse device, and train-carried brake-controlling means inductively influenced by the first named and the second named track impulse devices and co-operable with said braking mechanism for effecting the initial brake application and a 80 subsequent brake application according to traffic conditions.

46. A system of train signal and control embodying a track equipment including means for producing a magnetic field and a 90 source of energy, a vehicle equipment, and brake mechanism, said vehicle equipment including a plurality of train operation signals and including, also, electro-magnetic devices connected with said brake mechanism for automatically effecting a progressive speed reduction in the movement of a following vehicle with respect to a preceding vehicle, said vehicle equipment being provided with means influenced by the passage of lines of force 95 produced by the magnetic field of said track equipment to set into action said means operating, respectively, to produce a change in the signal indication and to effect the speed control.

47. In a system of train control, a track equipment embodying means for producing a magnetic field, a source of energy, and means for effecting a variation in the operative length of said magnetic field, in combination with a vehicle equipment embodying train control means and means influenced by said magnetic field of the track equipment for the operation of said train control means.

48. A system of train signal and control embodying electro-magnetic vehicle elements in circuit with a source of energy and train operation signals, electro-magnetic track elements in circuit with a source of energy for producing a magnetic field adapted to be traversed by said electro-magnetic vehicle elements and to effect the operation of said train control signals, brake mechanism, means responsive to a change in signal indication for operating said brake mechanism, and means whereby the brake mechanism may be operated at will and independently of said automatic operation in unison with the change in the signal indication.

49. In a train control, train-carried brak-

130

- ing apparatus, a trackway device responsive to traffic conditions, a separate trackway device also responsive to traffic conditions, and brake-controlling mechanism including 5 means responsive separately to inductive influences of the first named and second named trackway devices, said brake controlling mechanism being co-operable with said braking apparatus for initially applying said 10 braking apparatus under the influence of the first named trackway device and for subsequently applying the braking apparatus under the influence of the second named trackway device.
- 15 50. In a train control, train-carried braking apparatus, a track element responsive to traffic conditions, a second track element responsive to traffic conditions, brake-controlling mechanism co-operable with the 20 braking apparatus and inductively influenced by the first named and the second named track elements to effect an initial operation and a subsequent operation of said braking apparatus, and means for restoring to normal the 25 parts of said brake controlling mechanism affected by said track elements, or either of the same.
51. In a system of train signal and control, a track equipment including means possessing magnetic permeability, a vehicle equipment including train operation signals and an electro-magnetic element influenced by said magnetic field for causing said signals to indicate the proximity of the vehicle 30 to a distant vehicle, braking mechanism, a mechanically operated governor, and a second electro-magnet-element forming a part of said vehicle equipment and connected with said governor for controlling said brake 35 mechanism in accordance with a change in the displayed signal when said first named electro-magnetic vehicle element occupies a cooperative relation to the magnetic means of said track equipment.
- 40 52. In a system of train control, a track equipment including a plurality of track magnets and a source of energy for producing a magnetic field of predetermined length, and means for varying the operative length of 45 said magnetic field, in combination with a vehicle equipment movable within said magnetic field.
53. In a system of train control, a track equipment including a series of magnets 55 spaced at desired intervals and connected in circuit with a source of energy for producing a magnetic field of predetermined length, combined with vehicle carried means movable within said magnetic field and operating 60 to successively de-energize the track magnets of said series.
54. In a system of train control, a series 65 of track magnets connected in circuit with a source of energy and producing a magnetic field the operative length of which is de-
- pendent upon the distance separating a following vehicle from a leading vehicle, combined with a vehicle carried element movable within said magnetic field.
55. In a system of train control, a series 70 of track magnets connected in circuit with a source of energy for producing a magnetic field, and means dependent upon the distance intervening between two vehicles for effecting a variation in the operative length of said 75 magnetic circuit, combined with a vehicle carried element movable within said magnetic field.
56. In a system of train control, a series of 80 track magnets connected in circuit with a source of energy for producing a magnetic field, and means in circuit with said track magnets and dependent upon the distance separating two vehicles for effecting a variation in the operative length of the magnetic 85 field produced by said track magnets, in combination with a vehicle carried element movable within said magnetic field and operating to de-energize said track magnets.
57. In a system of train control, a track equipment including a plurality of series of 90 track magnets connected in circuit with a source of energy and producing a plurality of magnetic fields each of predetermined 95 length, and means for effecting a variation in the operative length of each magnetic field, combined with vehicle carried elements movable within the respective magnetic fields produced by said track magnets.
58. In a system of train control, a plurality of series of track magnets connected in circuit with a source of energy and producing magnetic fields of predetermined length, the magnetic field produced by one series of track magnets being in overlapping relation lengthwise of the track to the magnetic field produced by the other series of track magnets, in combination with vehicle carried 100 means movable within the magnetic fields produced by said plurality of series of track magnets.
59. In a system of train control, a plurality of series of track magnets connected in circuit with a source of energy and producing magnetic fields of predetermined length, the magnetic field produced by one series of track magnets being in overlapping relation lengthwise of the track to the magnetic field produced by the other series of track magnets, and means for effecting a variation in the operative length of each magnetic field, in combination with a plurality of vehicle elements movable within the respective fields 110 produced by said series of magnets.
60. In a system of train control, a plurality of series of track magnets connected in circuit with a source of energy and producing magnetic fields of predetermined length, and 115
- 65

- means dependent upon the distance separating two vehicles from one another for so controlling said track magnets of the two series as to effect a variation in the operative length of each magnetic field, in combination with vehicle carried elements movable within the magnetic fields produced by the respective series of track magnets.
61. In a system of train signal and control, the combination with means for producing a magnetic field adjacent to a track, of a plurality of signal relays carried by a vehicle and the armatures of which are movable within said magnetic field, a brake relay, a governor relay in series with said brake relay, and a plurality of other relays in circuit with said signal and governor relays for effecting the operation of the governor relay and the brake relay in accordance with a change in the signal indication brought about by de-energizing said signal relays.
62. In a system of train signal and control, the combination with means for producing a magnetic field adjacent to a track, of a plurality of vehicle carried signal relays movable within said magnetic field, a second vehicle carried relay, magnetic interferences for de-energizing said second named relay at predetermined intervals in the length of the track, brake mechanism, and brake controlling means connected for operation with said signal relays and the second named vehicle relay.
63. In a train control, braking mechanism, an inductive trackway element responsive to traffic control, said trackway element being located in one section of a track, a second trackway element located in a different section of a track and also responsive to traffic control, and brake-controlling mechanism including means movable within the fields of the first trackway element and the second trackway element respectively, said brake-controlling mechanism being operated to initiate a brake application when influenced by the first trackway element and to effect a subsequent brake application under the influence of the second trackway element.
64. In a system of train control, a series of track magnets connected with a source of energy and with the track rails for producing a magnetic field extending lengthwise of the track for a predetermined distance, and a relay connected with the track rails and with said track magnets for de-energizing the latter in the absence of a vehicle within a predetermined distance, combined with means controllable by the presence of a vehicle on the track for shunting said solenoid out of service and operable to establish the aforesaid magnetic field through said track magnets, and a vehicle carried element movable within said magnetic field.
65. In a train control, braking mechanism, a trackway device responsive to traffic control by a certain section of a track, a second trackway device responsive to traffic control, and brake-controlling mechanism including a plurality of train-carried elements inductively influenced by the first and second trackway devices, said brake-controlling mechanism being operable to initiate operation of the braking mechanism under the influence of the first named trackway device and actuated by the second trackway device to effect a brake application subsequent to the initial brake application.
66. A system of train signal and control embodying a track circuit adapted to be grounded in one block by a moving vehicle and including a source of energy and stationary track magnets arranged in series extending substantially throughout another block, and a vehicle equipment including elements positioned for movement through the fields afforded by said track magnets and separated from the latter by an intervening air gap, said vehicle equipment including speed control mechanism operated by said elements.
67. In a train control, braking mechanism, track magnets responsive to traffic control, and brake-controlling mechanism inductively influenced by said track magnets, said brake-controlling mechanism including a fluid check for retarding the action of said brake-controlling mechanism and including also a speed regulator operable by the motion of a vehicle and action to restrict the speed of said vehicle through the application of the braking mechanism dependent upon traffic conditions.
68. In a train control, braking mechanism, traffic responsive inductive trackway devices, a vehicle-carried brake-coil, and a plurality of vehicle-carried brake-controlling magnets in circuits influenced by said traffic responsive trackway devices, one of said trackway devices operating to so influence the brake-controlling magnets as to initiate a brake application and another of said trackway devices operating through said brake-controlling magnets to effect a subsequent brake application in accordance with and dependent upon traffic conditions and the speed of the vehicle.
69. In an inductive train control system, vehicle-carried braking mechanism, a succession of traffic responsive trackway devices, and brake-controlling mechanism including a plurality of receiving coils selectively influenced by said trackway devices and speed regulating coils responsive to the control of the first mentioned coils for restricting through the action of the braking mechanism the speed of a vehicle in accordance with traffic conditions.
70. In a train control system, vehicle-carried braking mechanism, traffic responsive trackway devices, a plurality of normally energized vehicle-carried coils influenced in

ductively by the trackway devices and governing the display of signals, speed regulating mechanism, and other vehicle-carried coils in circuit with armatures controlled by the first named coils and governed by the action of said speed regulating mechanism.

71. In a train control system, vehicle-carried braking mechanism, traffic responsive trackway devices, a plurality of vehicle-carried coils influenced inductively by said trackway devices and operable for governing signal indications on a vehicle, a vehicle driven speed governor, and other coils in circuit with armatures controlled by said signal governing coils and controllable by the speed governor to effect successive operations of said braking mechanism.

72. In a train control system, braking mechanism, traffic responsive trackway devices, a plurality of signal-governing coils inductively influenced by the trackway devices in accordance with traffic conditions, a vehicle-driven speed governor and a plurality of contacts operated thereby, and a plurality of other coils in circuit with armatures controlled by signal governing coils and controllable by the corresponding contacts of the speed governor for effecting brake applications dependent upon traffic conditions and the speed of the vehicle.

73. In a train control system, a vehicle-carried braking mechanism, a succession of traffic controlled track magnets, brake-controlling mechanism inductively influenced by said track magnets and operable for effecting a succession of brake applications, and wayside means for inductively restoring to normal parts of the brake-controlling mechanism affected by said track magnets for the operation of said braking mechanism.

74. In a train control system, vehicle-carried braking mechanism, traffic controlled track magnets, a plurality of signal-governing coils each provided with a fluid check and said coils being inductively influenced by said track magnets, and means responsive to the control of said signal-governing coils for controlling the action of said braking mechanism to effect successive brake applications in accordance with traffic conditions.

75. In a train control system, vehicle-carried braking mechanism and a track element to inductively influence a vehicle-carried brake-controlling mechanism, said mechanism including a vehicle driven speed governor comprising a plurality of contacts and a plurality of coils corresponding to and controlled by said speed governor contacts for effecting brake applications by said braking mechanism.

76. In a train control system, the combination with vehicle-carried equipment comprising a braking mechanism and a speed-governor, of traffic controlled inductive

trackway means for effecting successive applications of said brake mechanism whereby the train speed is initially reduced within permissible speed limits determined by said speed-governor and the successive brake applications so reduces the train movement as to bring it to a stop.

77. In a train control system, the combination with a train carried braking mechanism, of a succession of traffic controlled inductive trackway means positioned substantially at the entrance to a block along the right of way, train-carried control means to cooperate with said trackway means for effecting successive braking applications, and thereby secure a progressive reduction in the speed of a train in accordance with traffic conditions and inductive resetting means positioned along said right of way for resetting the train-carried control means.

78. In a control system for effecting automatic braking on a vehicle, the combination of a controller responsive to external magnetic influences, means responsive to the speed of a vehicle, means for effecting a brake application, and means actuated by an external magnetic influence to render the brake applying means responsive to a subsequent magnetic influence and to the speed responsive means conjointly.

79. In a system of train control, the combination with braking mechanism and receiving means comprising an electro-magnet on a vehicle, of trackway devices for setting up local magnetic influences to change the condition of said electro-magnet, brake-controlling means, said receiving means being influenced by such change to effect successive brake applications, and means responsive to the movement of the vehicle for retarding the speed thereof at periods following the brake applications.

80. The combination with a track and a vehicle moving thereon, of impulse creating means located at successive points along the track, means upon the vehicle for effecting a brake application, receiving means upon the vehicle for the impulses created by the track means, means shifted by the reception of an impulse to place the brake applying means under the control of a succeeding impulse only if the shiftable means are in a shifted position, and means actuated from the track for restoring the shifted means to normal position.

81. The combination with a vehicle having a braking system thereon and a track along which the vehicle moves, of inductive means located along the track for imparting a primary influence to the vehicle, inductive means located along the track for imparting a secondary influence to the vehicle, brake applying means on the vehicle including a speed responsive device driven from the wheels of the vehicle, and means operable

only by successive primary and secondary influences for rendering said brake applying means effective to establish a restricted speed limit that the vehicle can not exceed without an automatic brake application.

82. In a control system for effecting automatic braking on a vehicle, the combination of means for receiving inductive impulses from the track, means responsive to the speed of the vehicle, means for effecting a brake application, and means actuated by the reception of an impulse to render the brake applying means responsive to the joint action of a subsequent impulse and to the speed responsive means.

83. In a train control system braking mechanism, train-carried brake-controlling means for setting into action the braking mechanism, said brake controlling means including a relay, a normally closed maintaining circuit therefor, a circuit breaker in said circuit and an auxiliary circuit for said relay, and inert magnetic track elements placed at successive points along the track adapted to influence said brake controlling means by opening said circuit breaker, a closure of the auxiliary circuit preventing actuation of the brake controlling means in spite of the opening of said circuit breaker.

84. In a train control system, a succession of track blocks, a normally inert track impulse device in each block, train-carried brake-controlling means, including a normally energized electropneumatic brake applying means, two relays for controlling the brake applying means, and an electromagnetic device, the magnetic reluctance of which is influenced by the track element to cause deenergization of the said relays and the actuation of the electropneumatic brake applying means.

85. The combination with a track and a vehicle moving thereon, of a brake system including means for manually controlling brake applications, and means located along the track for imparting a braking influence for automatically effecting an initial braking normally inert magnetic means located along the track and energized from the vehicle for imparting a subsequent braking influence to the vehicle, and means conjointly controlled by the first and second named braking influences for effecting a subsequent braking.

86. The combination with a vehicle having a braking system thereon, and a track along which the vehicle moves, of normally inert magnetic means located along the track for imparting an initial braking impulse to the vehicle when energized by flux generated on the vehicle, normally inert means located along the track for imparting a subsequent braking impulse to the vehicle when energized by flux generated on the vehicle, and means for nullifying the application of the

last named braking impulse unless the train is exceeding a safe speed at the time of receipt of said braking impulse.

87. The combination with a vehicle having a braking system and means to generate a magnetic flux on the vehicle, and a track along which the vehicle moves, of normally inert magnetic means located along the track for imparting an initial braking impulse to the vehicle when energized by flux from the vehicle, normally inert magnetic means located along the track for imparting a subsequent braking impulse to the vehicle when energized by flux generated on the vehicle, and means for nullifying the application of the last named braking impulse unless the train exceeds a predetermined speed after the receipt of said braking action.

88. In an inductive train-control system a vehicle having a braking system and a speed-responsive device on the vehicle, and normally inert magnetic means located along the track and energized by magnetic flux from the vehicle for effecting an initial brake application, track-reset mechanism, and means controlled by the speed-responsive device after the initial brake application and prior to the action of the reset mechanism for effecting a subsequent brake application.

89. The combination with a track and with a vehicle moving thereon, of means for effecting when actuated an initial brake application, means for effecting a subsequent brake application, reset means located along the track, and magnetic means located along the track energized by flux from the vehicle and controlling the initiation of brake applications, the actuation of the subsequent brake application means being also controlled by the speed of the train prior to its passage over the reset means.

90. In a train braking system, the combination with a normally energized coil controlling a primary braking thereof, a normally energized coil controlling a secondary braking thereof, a circuit breaker for the circuits of said coils effective in respect to the second coil only upon successive operation thereof, and means under the control of normally inert magnetic track elements energized from the vehicle to actuate said circuit breaker and two speed operated contactors to prevent deenergization of the two coils in spite of the actuation of the circuit breaker.

91. In a system of train control, the combination with vehicle carried braking mechanism of magnetic track impulse devices controllable by traffic conditions and each operating to set up a local magnetic influence the establishment of which is dependent upon traffic conditions and energization of train-carried parts, brake-controlling means actuated by a track magnet for initiating the operation of said braking mechanism, and ad-

ditional brake-controlling means also influenced by a track impulse device for affecting a subsequent application of the braking mechanism.

5 92. In a system of train control, the combination with braking mechanism, of a succession of magnetic track impulse devices controllable by traffic conditions, each impulse device being responsive to such conditions and each operating to set up a local magnetic influence on energization by train-carried parts, and train-carried means comprising a plurality of electro responsive devices and a circuit breaker controlling same, 10 a brake control device under the control of the electro responsive devices, an auxiliary circuit to control said brake control device, said train-carried means movable within the magnetic influence of said track impulse devices and actuated thereby for setting into action said braking-mechanism by deenergization of the brake control device unless such deenergization is prevented by closure of the auxiliary circuit.

25 93. In a system of train control, the combination with braking mechanism, of magnetic track impulse devices controllable by traffic conditions and each responsive to such conditions for setting up a local magnetic influence on energization by train-carried parts, a brake-controlling member, a plurality of other brake-controlling members each governed by the magnetic influences of said track impulse devices and each cooperating 30 with the first named brake-controlling member for effecting successive applications of said braking mechanism dependent upon the traffic conditions.

40 94. In a system of train control, the combination with braking mechanism of magnetic track impulse devices controllable by traffic conditions and responsive to such conditions for setting up a succession of local magnetic influences on energization by train-carried 45 parts, a brake-controlling coil, a plurality of other brake-controlling coils selectively responsive to the influence of the track impulse devices, said second named coils cooperating with the first named coil for effecting successive brake applications dependent upon traffic 50 conditions.

55 95. In a system of train control, the combination with braking mechanism, of magnetic track impulse devices controllable by traffic conditions and responsive to such conditions for setting up a succession of local magnetic influences on energization by train-carried parts, and automatic brake-controlling means movable relatively to the track 60 impulse devices and influenced thereby when the track is occupied ahead of the train, said brake controlling means comprising a stick relay, a valve controlled by a normally closed electric circuit including a contact controlled 65 by the stick relay, an auxiliary circuit to con-

trol said valve and a time delay to permit closure of the auxiliary circuit and prevent de-energization of the valve in spite of the influence of the track impulse device.

70 96. The combination with a vehicle having a braking system thereon and a track along which the vehicle moves, of normally inert magnetic means located along the track and energized from the vehicle for imparting a primary influence to the vehicle, means located along the track for imparting a secondary influence to the vehicle, brake applying means on the vehicle including a speed responsive device driven from the wheels of the vehicle, and means operable only by successive primary and secondary influences for rendering said brake applying means effective to establish a restricted speed limit that the vehicle cannot exceed without an automatic brake application.

75 In testimony whereof I have hereunto subscribed my name.

CHARLES W. BREWSTER.
